TELEPHONE SYSTEM

Seth E. Peterson, Chicago, and Morris E. Griffins, Riverside, Ill., assignors to Associated Electric Laboratories, Inc., Chicago, Ill., a corporation of Delaware

Application April 11, 1940, Serial No. 329,086

43 Claims. (Cl. 179—27)

The present invention relates to telephone systems and more particularly to improvements in telephone systems of the semi-automatic type.

In a telephone system of the semi-automatic type a call initiated on a telephone line is automatically extended by associated switching apparatus to an operator position to be answered; and after the call is answered at the operator position, the operator thereat controls an associated switch train to extend the call to the desired destination. In a telephone system of this character the switch train associated with the operator position frequently comprises different types of automatic switches, rendering it necessary for the operator to manipulate corresponding different types of calling devices at the operator position in order to control the different types of automatic switches in the associated switch train. As a result of this type of control, a larger number of errors is made and more delay is encountered at the operator position in extending calls than is desirable.

Accordingly, it is an object of the present invention to provide in a telephone system of the type described comprising an operator position and a switch train including a number of different types of automatic switches, an improved unitary calling device at the operator position which is operative selectively to control indiscriminately the different types of automatic switches in the associated switch train.

Another object of the invention is to provide in a telephone system of the type described including an operator position, improved switching apparatus for routing calls to the operator position to be answered.

Another object of the invention is to provide in a signaling system, an improved register arrangement for selectively controlling the operation of an associated automatic switch.

Another object of the invention is to provide in a signaling system, an improved register arrangement for selectively controlling the operation of an associated repeater which is operative to repeat switch control impulses.

A further object of the invention is to provide in a signaling system, an improved repeater which is operative to repeat switch control impulses.

A further object of the invention is to provide in a signaling system comprising a repeater which is operative to repeat switch control impulses, an improved arrangement including an impulse generator for selectively controlling the operation of the repeater.

A further object of the invention is to provide

in a signaling system comprising a number of repeaters each of which is operative to repeat switch control impulses, an improved arrangement including an impulse generator commonly associated with the repeaters for selectively controlling the operation of the repeaters.

A further object of the invention is to provide in a signaling system, an improved impulse generator which is adapted to be utilized in a repeater network.

The features of the present invention are illustrated as being incorporated in a telephone system comprising a central exchange terminating a plurality of manual telephone lines and a distant exchange terminating a plurality of manual telephone lines, the central exchange and the distant exchange being interconnected by two groups of one-way trunk lines extending therebetween. The central exchange comprises 15 an operator switchboard provided with a number of operator positions; and each exchange comprises an automatic switch train, the automatic switch train in the central exchange including a repeater network.

20 In accordance with one feature of the invention the telephone system comprises a trunk including first and second line conductors, switching apparatus having access to the trunk, an automatic switch terminating the trunk, a plurality of lines accessible to the automatic switch, means for causing the automatic switching apparatus to seize the trunk when the trunk is idle, means controlled by the seizure of the trunk for impressing a predetermined potential upon the first

25 line conductor of the trunk, means controlled when the predetermined potential is impressed upon the first line conductor of the trunk for conditioning the automatic switch, and means controlled when the automatic switch is conditioned for rendering busy the trunk. Also the system comprises means for operating the automatic switch after it is conditioned, thereby to cause the automatic switch to seize one of the lines, and means for initiating the release 30 of the automatic switch, the automatic switch being so connected and arranged that it is adapted to be completely released when the release thereof is initiated. Further the system comprises means controlled in the event the automatic switch fails completely to release for impressing a predetermined potential upon the second line conductor of the trunk, and means controlled when the predetermined potential is impressed upon the second line conductor of the trunk for rendering busy the trunk.

35 40 45

50

Further the system comprises a given telephone line associated with the switching apparatus, the switching apparatus being operated in response to the presence of a calling condition upon the given telephone line to seize the trunk when the trunk is idle. Also the telephone system comprises an operator position, means controllable from the operator position for selectively operating the automatic switch, the automatic switch being operative in a first predetermined manner to seize one of the lines accessible thereto and in a second predetermined manner without seizing one of the lines accessible thereto, means included in the automatic switch and controlled by the operation thereof in the second manner for causing the release of the automatic switch, and means controlled by the release of the automatic switch for rendering idle the trunk and for locking out of service the given telephone line in the event there is a calling condition thereon.

In accordance with another feature of the invention the system comprises a register, means for registering different digits in the register, an automatic switch including a switching mechanism and an impulse responsive motor for operating the switching mechanism and an impulse transmitter operative to transmit impulses to the motor, means for connecting the register to the switch, means for initiating operation of the impulse transmitter, means controlled revertively from the switch in accordance with the operation of the impulse transmitter to transmit impulses to the motor for clearing the register of the digit registered therein, whereby the register is cleared of the digit registered therein when the number of impulses transmitted from the impulse transmitter to the motor corresponds to the digit registered in the register, and means controlled when the register is cleared of the digit registered therein for arresting operation of the impulse transmitter. More particularly, the impulse transmitter in the switch is of the step-by-step type, the impulse transmitter being operative to transmit a direct impulse to the motor and a revertive impulse to the register upon each step thereof; and the control arrangement for the impulse transmitter includes means for initiating step-by-step operation of the impulse transmitter, and means controlled when the number of revertive impulses transmitted from the impulse transmitter to the register corresponds to the digit registered therein for arresting step-by-step operation of the impulse transmitter.

In accordance with a further feature of the invention the system comprises a repeater including an impulse transmitter operative to transmit impulses from the repeater, means for connecting the register to the repeater, means for initiating operation of the impulse transmitter, means controlled revertively from the repeater in accordance with the operation of the impulse transmitter for clearing the register of the digit registered therein, whereby the register is cleared of the digit registered therein when the number of impulses transmitted from the repeater corresponds to the digit registered in the register, and means controlled when the register is cleared of the digit registered therein for arresting operation of the impulse transmitter. More particularly, the transmitter in the repeater is operative to transmit switch control impulses and register control impulses at a predetermined rate, and the arrangement for controlling the operation of the repeater includes means for initiating operation of the impulse transmitter and means

controlled when the number of register control impulses transmitted from the impulse transmitter to the register corresponds to the digit registered therein for arresting operation of the impulse transmitter.

In accordance with a further feature of the invention the system comprises a number of registers, means for registering different digits in the registers, switching means operative through a number of cycles successively to connect and disconnect the registers and the repeater, the switching means being operative through a given cycle to connect a given register to the repeater and then to disconnect the given register from the repeater, the impulse transmitter included in the repeater being operative through a cycle to transmit a series of switch control impulses, means for initiating a cycle of operation of the switching means, means controlled when a register is connected to the repeater for initiating a cycle of operation of the impulse transmitter, and means controlled revertively from the repeater in accordance with the operation of the impulse transmitter for completing a cycle of operation of the switching means and then for initiating another cycle of operation of the switching means, whereupon one of the registers is disconnected from the repeater and then another of the registers is connected to the repeater, the last-mentioned means being controlled when the number of impulses transmitted from the repeater corresponds to the digit registered in the one of the registers. Further the system comprises means controlled when a cycle of operation of the switching means is completed for completing a cycle of operation of the impulse transmitter.

In accordance with a further feature of the invention the system comprises an impulse generator, means for connecting the register to the repeater and for connecting the repeater to the impulse generator, means controlled when the repeater is connected to the impulse generator for initiating operation of the impulse transmitter, means controlled when the number of impulses in the series of register control impulses transmitted from the impulse transmitter to the register corresponds to the digit registered therein for disconnecting the register from the repeater, and means controlled when the register is disconnected from the repeater for arresting operation of the impulse transmitter and for disconnecting the repeater from the impulse generator. More particularly, the impulse generator is operative repeatedly through a cycle to transmit a start impulse and then at least one control impulse; and the arrangement for controlling the repeater includes a control network operative to condition the impulse transmitter in response to a start impulse transmitted from the impulse generator and then to cause operation of the impulse transmitter after it is conditioned in response to control impulses transmitted from the impulse generator, thereby to prevent operation of the impulse transmitter to transmit a series of switch control impulses including a mutilated switch control impulse, and means for selectively operating the control network, thereby to cause the repeater to transmit a series of switch control impulses comprising different numbers of switch control impulses.

In accordance with a further feature of the invention the system comprises a repeater network including a number of individual repeaters

commonly associated with the impulsing generator, a number of calling devices, means for selectively connecting the calling devices to the repeaters, and means including the calling devices for selectively controlling the operation of the repeaters from the impulse generator. More particularly, the repeater network is so connected and arranged that operation of the impulse generator is initiated when one of the repeaters is connected thereto, and operation of the impulse generator is arrested when each of the repeaters is disconnected therefrom.

In accordance with a further feature of the invention the impulse generator comprises a control network including first and second relays, first and second conductors, and means for impressing cyclically at a predetermined rate upon the first conductor and then upon the second conductor a predetermined potential, the control network being so connected and arranged that each odd time the potential is impressed upon the first conductor the first relay is operated, each odd time the potential is impressed upon the second conductor the second relay is operated, each even time the potential is impressed upon the first conductor the first relay is restored, and each even time the potential is impressed upon the second conductor the second relay is restored, whereby the first and second relays are controlled cyclically at one-half the predetermined rate. Also the impulse generator includes an impulse transmitting network governed by the cyclical control of the first and second relays. Also the impulse generator includes a signal and means governed by a predetermined departure by the first and second relays from the cyclical control at one-half the predetermined rate for controlling the signal.

In accordance with a further feature of the invention the network in the impulse generator comprises a timing relay, first and second condensers, a first series circuit for charging the first condenser and for energizing the relay, a second series circuit for charging the second condenser and for energizing the relay, a first series path for discharging the first condenser and for energizing the relay, a second series path for discharging the second condenser and for energizing the relay, cyclically operating control means for completing the first circuit and the second path and then for completing the second circuit and the first path, thereby intermittently to energize the timing relay in order to cause intermittent operation thereof, and means governed by the intermittent operation of the timing relay.

Further features of the invention pertain to the particular arrangement of the circuit elements thereof, whereby the above-outlined and additional operating features are attained.

The novel features believed to be characteristic of the invention are set forth with particularity in the appended claims. The invention, both as to its organization and method of operation, together with further objects and advantages thereof, will best be understood by reference to the following specification taken in connection with the accompanying drawings in which Figure 1 illustrates the general arrangement of a telephone system including a central exchange and a distant exchange and embodying the present invention; and Figs. 2 to 6, inclusive, taken together, illustrate the details of a system having incorporated therein the features of the invention, as briefly outlined above.

DESCRIPTION OF THE APPARATUS INCORPORATED IN THE SYSTEM

Referring now more particularly to Fig. 1 of the drawings, the telephone system there illustrated comprises a central exchange 20, a distant exchange 70, a first group of one-way trunk lines extending from the distant exchange 70 to the central exchange 20, including the trunk line 50, and a second group of one-way trunk lines extending from the central exchange 20 to the distant exchange 70, including the trunk line 60. The central exchange 20 is of the semi-automatic type serving a number of manual subscriber substations, including the subscriber substations C and D. A telephone line having a line circuit individually associated therewith extends to each subscriber substation in the central exchange 20; the telephone lines 41 and 42 having the line circuits 45 and 46 respectively associated therewith extend to the subscriber substations C and D, respectively. The distant exchange 70 is of the semi-automatic type serving a number of manual subscriber substations, including the subscriber substations A and B. A telephone line having a line circuit and a non-numerical automatic switch individually associated therewith extends to each subscriber substation in the distant exchange 70; the telephone lines 71 and 72 having the line circuits 75 and 76 and the non-numerical automatic switches 78 and 79 respectively associated therewith extend to the subscriber substations A and B, respectively.

Each trunk line in the first group of trunk lines extending from the distant exchange 70 to the central exchange 20 terminates in a trunk circuit in the distant exchange 70 and in a selector repeater in the central exchange 20. For example, the trunk line 50 in the first group of trunk lines terminates in the trunk circuit 80 in the distant exchange 70 and in the selector repeater 55 in the central exchange 20. Each trunk line in the second group of trunk lines extending from the central exchange 20 to the distant exchange 70 terminates in a repeater in the central exchange 20 and in an incoming selector switch in the distant exchange 70. For example, the trunk line 60 in the second group of trunk lines terminates in the repeater 65 in the central exchange 20 and in the incoming selector switch 90 in the distant exchange 70. Also the distant exchange 70 comprises a switch train including, in addition to the group of non-numerical automatic switches and the group of incoming selector switches, a number of groups of connector switches, one of the groups of connector switches including the connector switch 95. Each non-numerical automatic switch has access to each of the trunk circuits; each of the incoming selector switches has access to the connector switches in the various groups of connector switches; while the connector switches in the various groups of connector switches have access to the various groups of telephone lines.

Also the central exchange 20 comprises, in addition to the group of selector repeaters and the group of repeaters, a local automatic switch train 21, a switchboard provided with a number of operator positions including the first operator position 30, a main master impulse generator 22, and an auxiliary master impulse generator 23. Preferably each operator position is identical to the first operator position 30, which comprises operator telephone and control equip-

ment 31, operator connecting apparatus 32, and a key sender 33.

Each of the selector repeaters is accessible to each of the operator positions, thereby to allow the operator at any operator position to answer a call from the distant exchange 70 to the central exchange 20 on the selector repeater. Furthermore, each selector repeater has access to each repeater and to the local automatic switch train 21. The local automatic switch train 21 is accessible to each telephone line in the central exchange 20, and to each operator position, and has access to each operator position, to each telephone line in the central exchange 20 and to each of the repeaters. Finally, the main master impulse generator 22 and the auxiliary master impulse generator 23 are commonly associated with the repeaters and are operative to control the various repeaters and the key senders at the various operator positions, in a manner more fully explained hereinafter.

Each subscriber substation in the central exchange 20 and each subscriber substation in the distant exchange 70 is provided with substation equipment including a telephone instrument and a ringer. The line circuits individually associated with the telephone lines in both the central exchange 20 and the distant exchange 70 are of conventional connection and arrangement. Also the non-numerical automatic switches in the distant exchange 70 are of a conventional type; while the incoming selector switches and the connector switches in the distant exchange 70 are of the well-known Strowger type.

Preferably, each of the trunk circuits in the distant exchange 70 is identical to the trunk circuit 80 which comprises, as best shown in Fig. 2, a number of relays including a line relay R220, a hold relay R230, a busy relay R240 and a bridge relay R250, connected and arranged in a manner more fully described subsequently.

Preferably, each of the selector repeaters in the central exchange 20 is identical to the selector repeater 55 which comprises, as best shown in Fig. 3, a switching mechanism 300 of the 100-point Strowger type, including a carriage provided with a wiper set including the wipers 301, 302, 303 and 304, the wipers mentioned being capable of both vertical and rotary movements. Further the mechanism 300 comprises a circumferentially disposed main contact bank associated with the wiper set, the wiper set having access to a group of one hundred lines terminated by the main contact bank. Also the mechanism 300 is provided with a vertical magnet M305 for moving the wiper set thereof in the vertical direction, a rotary magnet M307 for moving the wiper set thereof in the rotary direction, and a release magnet M309 for releasing the wiper set thereof and for causing the wiper set to be returned to its normal position. Finally the switching mechanism 300 has a number of switch springs S310, S311, S312, S313, S314, S315 and S318 operatively associated therewith, which are controlled in accordance with the movements of the wiper set thereof, in a manner more fully explained subsequently.

Also the selector repeater 55 comprises a number of relays including a line relay R325, two hold relays R330 and R360, a start relay R340, a send relay R345, an answer relay R350, an impulse relay R370, a control relay A375, a transfer relay R380 and a switching relay R390, connected and arranged in a manner more fully described subsequently.

Preferably, each of the repeaters in the central exchange 20 is identical to the repeater 65 which comprises, as best shown in Fig. 5, a repeater transformer 500 and a number of relays including a dial impulse relay R510, an answer relay R515, a control relay R520, a start relay R525, a revertive impulse relay R530, a digit relay R535, a pickup relay R540, a hold relay R550 and a timing relay R560, connected and arranged in a manner more fully described subsequently.

The local automatic switch train 21 is of a well-known type, including finder switches, selector switches and connector switches, each being of the all-relay type, wherein the selector switches and the connector switches are operative to transmit revertive control impulses, in a manner more fully explained subsequently.

Preferably, each operator position in the central exchange 20 is connected and arranged in a conventional manner, the operator telephone and control equipment 31, the operator connecting apparatus 32 and the key sender 33 individually associated with the first operator position 30 being of well-known types. More particularly, the operator telephone and control equipment 31 comprises a telephone instrument, not shown, and a number of control keys, not shown, for setting up and supervising connections at the first operator position 30; the key sender 33 comprises a key set, not shown, and a number of registers including the first register 400; and the operator connecting apparatus 32 comprises a number of connect keys, individually associated with the trunks in a first group of trunks extending to the group of selector repeaters and a second group of trunks extending to the local automatic switch train 21, and a number of supervisory lamps. For example, the connect key K440 in the operator connecting apparatus 32 is individually associated with the trunk 35 extending to the selector repeater 55 and has individually associated therewith a line lamp L447 and an answer lamp L446; while the connect key K445 is individually associated with the trunk 34 extending to the local automatic switch train 21 and has individually associated therewith a line lamp and an answer lamp, not shown.

Preferably, both the main master impulse generator 22 and the auxiliary master impulse generator 23 in the central exchange 20 are identical and are commonly associated with each repeater in the associated group of repeaters. As best shown in Fig. 6, the main master impulse generator 22 comprises two impulse relays R600 and R610, two cycle relays R620 and R630, a start relay R640, a timing relay R650, a lockout relay R660 and a hold relay R670, connected and arranged in a manner more fully described subsequently. Also the main master impulse generator 22 comprises an interrupter I680, two supervisory lamps L617 and L618 and a reset key K676. The master impulse generators 22 and 23 are so connected and arranged that the main master impulse generator 22 is normally operatively associated with the repeaters in the associated group of repeaters and is adapted, in the event of failure thereof, operatively to associate the auxiliary master impulse generator 23 with the repeaters in the associated group of repeaters.

A better understanding of the connection and arrangement of the telephone system will be facilitated from a consideration of the general operation of the various pieces of apparatus incor-

porated therein incident to the completion and handling of various calls at the first operator position 30 in the central exchange 20, as will appear hereinafter.

General operation of the system

Considering now the general operation of the system with reference to Fig. 1 of the drawings, it is noted that calls initiated at the subscriber substation in both the central exchange 20 and in the distant exchange 70 are answered at an operator position in the central exchange 20 and then extended from the operator position to the various subscriber substations in both the central exchange 20 and in the distant exchange 70.

For example, when a call is initiated at the subscriber substation C in the central exchange 20, the line circuit 45 individually associated with the telephone line 41 is controlled, thereby to cause the local automatic switch train 21 to operate and seize the telephone line 41 and an idle trunk, such as the trunk 34, extending to the operator positions. When the trunk 34 is thus seized, signals are transmitted to the various operator positions in the central exchange 20; whereupon the operator at one of the operator positions, such, for example, as the first operator position 30, answers the call by operating the connect key K445 in the operator connecting apparatus 32 individually associated with the trunk 34 and is advised concerning the extension of the call.

In the event the call is to be extended to another subscriber substation in the central exchange 20, such, for example, as the subscriber substation D, the operator at the first operator position 30 then registers in the key sender 33 the appropriate digits in order to control the operation of the local automatic switch train 21. The local automatic switch train 21 then operates to seize the telephone line 42 extending to the subscriber substation D. The subsequent operation of the local automatic switch train 21 depends upon the idle or busy condition of the subscriber substation D in accordance with conventional practice. The operator at the first operator position 30 then returns the connect key K445 in the operator connecting apparatus 32 back to its normal position, thereby to release the apparatus at the first operator position 30.

On the other hand, in the event the call is to be extended to a subscriber substation in the distant exchange 70, such, for example, as the subscriber substation B, the operator at the first operator position 30 then registers in the key sender 33 the appropriate digits in order to control the operation of the local automatic switch train 21. The local automatic switch train 21 then operates to seize an idle trunk in the group of trunks extending to the group of repeaters, such, for example, as the trunk 37, extending to the repeater 65. The subsequent operation of the repeater 65 and the apparatus in the distant exchange 70 to extend the call to the subscriber substation B in the distant exchange 70 is explained more fully hereinafter. After operation of the repeater 65 and the previously mentioned apparatus in the distant exchange 70, the operator at the first operator position 30 returns the connect key K445 in the operator connecting apparatus 32 back to its normal position, thereby to release the apparatus at the first operator position 30.

For example, when a call is initiated at the

subscriber substation A in the distant exchange 70, the line circuit 75 individually associated with the telephone line 71 is controlled, thereby to cause the non-numerical automatic switch 78 to seize an idle trunk in the group of trunks extending to the associated trunk circuits, such, for example, as the trunk 81 extending to the trunk circuit 80. When the trunk 81 is thus seized the trunk circuit 80 operates, thereby to cause operation of the selector repeater 55 by way of the associated trunk line 50, whereupon signals are transmitted to the various operator positions in the central exchange 20. The operator at one of the operator positions, such, for example, as the first operator position 30, answers the call by operating the connect key K440 in the operator connecting apparatus 32 individually associated with the trunk 35 extending to the selector repeater 55 and is advised concerning the extension of the call.

In the event the call is to be extended to a subscriber substation in the central exchange 20, such, for example, as the subscriber substation D, the operator at the first operator position 30 then registers in the key sender 33 the appropriate digits in order to control the operation of the selector repeater 55 and the local automatic switch train 21. The local automatic switch train 21 then operates to seize the telephone line 42 extending to the subscriber substation D. The subsequent operation of the local automatic switch train 21 depends upon the idle or busy condition of the subscriber substation D, as previously noted. The operator at the first operator position 30 then returns the connect key K440 in the operator connecting apparatus 32 back to its normal position, thereby to release the apparatus at the first operator position 30.

On the other hand, in the event the call is to be extended to a subscriber substation in the distant exchange 70, such, for example, as the subscriber substation B, the operator at the first operator position 30 then registers in the key sender 33 the appropriate digits in order to control the operation of the selector repeater 55, whereupon the selector repeater 55 operates to seize an idle trunk in the group of trunks extending to the group of repeaters, such, for example, as the trunk 37 extending to the repeater 65.

When the trunk 37 is thus seized the repeater 65 operates in order to condition the incoming selector switch 90 in the distant exchange 70 by way of the associated trunk line 60 and to initiate operation of the main master impulse generator 22, in the event it is not already operating. The main master impulse generator 22 causes impulses corresponding to the impulses registered in the various registers in the key sender 33 to be transmitted by way of the repeater 65 over the trunk line 60 to the incoming selector switch 90, thereby to cause operation of the incoming selector switch 90 and the succeeding connector switch. More particularly, the incoming selector switch 90 is operative to select an idle one of the connector switches in one of the groups of connector switches, such, for example, as the connector switch 95. The connector switch 95 is then operated to seize the telephone line 72 extending to the subscriber substation B in the distant exchange 70. The subsequent operation of the connector switch 95 depends upon the idle or busy condition of the subscriber substation B in accordance with conventional practice.

After the repeater 65 is thus operated, the operator at the first operator position 30 returns the connect key K440 in the operator connecting apparatus 32 back to its normal position, thereby to release the apparatus at the first operator position 30.

It is noted that the release of an established connection between two subscriber substations in the central exchange 20, between two subscriber substations in the distant exchange 70 and between a subscriber substation in the central exchange 20 and a subscriber substation in the distant exchange 70 is primarily under the control of the subscriber at the calling subscriber substation and is effected when the subscriber at the calling subscriber substation performs a release operation thereat.

Further it is noted that, in the event a false call is initiated on a telephone line in the distant exchange 70, such as the telephone line 71 extending to the subscriber substation A, the call is extended by way of one of the trunk lines, such as the trunk line 50, and the associated selector repeater 55 to one of the operator positions in the central exchange 20 to be answered. For example, the false call may be answered at the first operator position 30 in the manner previously explained. After the operator at the first operator position 30 determines that the call is a false call she operates the key sender 33, thereby to cause the selector repeater 55 to be operated in accordance with a single digit, in a manner more fully described hereinafter. When the selector repeater 55 is thus operated the line circuit 75 individually associated with the telephone line 71 is operated in order to lock the telephone line 71 out of service. The telephone line 71 remains locked out of service until the fault thereon is removed.

As previously noted, the main master impulse generator 22 is operative to control each repeater in the associated group of repeaters and is so connected and arranged that, in the event it fails properly to operate, it operates subsequently, thereby to initiate operation of the auxiliary master impulse generator 23, whereby the auxiliary master impulse generator 23 is rendered operative to control each repeater in the associated group of repeaters. Finally it is noted that both the main master impulse generator 22 and the auxiliary master impulse generator 23 are operative to control simultaneously a large number of repeaters in the associated group of repeaters, the repeaters in the associated group being divided into odd and even subgroups.

Detailed operation of the system

A call from a subscriber substation in the distant exchange 70, such as the subscriber substation A, is first initiated by removing the receiver of the telephone instrument thereat from its associated switchhook, thereby to cause operation of the line circuit 75 individually associated with the telephone line 71 extending to the subscriber substation A. Upon operating, the line circuit 75 marks the telephone line 71 extending to the subscriber substation A as busy to the switches having access thereto and initiates operation of the non-numerical automatic switch 78 individually associated with the telephone line 71, whereupon the non-numerical automatic switch 78 operates to seize an idle trunk accessible thereto, such as the trunk 81 extending to the trunk circuit 80, the trunk 81 being marked as idle by the absence of ground potential upon the

control conductor C203 thereof. When the non-numerical automatic switch 78 seizes the trunk 81 a loop circuit is completed between the subscriber substation A and the line relay R220 in the trunk circuit 80, this circuit extending from ground by way of the lower winding of R220 to the line conductor C202 of the trunk 81 and from battery by way of the upper winding of R220 to the line conductor C201 of the trunk 81, the line conductors C201 and C202 of the trunk 81 being connected by way of the non-numerical automatic switch 78 and the telephone line 71 to the subscriber substation A. When this loop circuit is completed the line relay R220 operates to interrupt, at the contacts 223, a circuit traced hereinafter for energizing the winding of the busy relay R240 to prepare, at the contacts 221, a circuit traced hereinafter for energizing the winding of the bridge relay R250 and to complete, at the contacts 224, a path for applying ground potential to the line conductor C211 of the trunk line 50 extending between the trunk circuit 80 in the distant exchange 70 and the selector repeater 55 in the central exchange 20. 10 The path for applying ground potential to the line conductor C211 of the trunk line 50 extends from ground by way of the contacts 233 and 224 to the line conductor C211 of the trunk line 50. 15 The application of ground potential to the line conductor C211 of the trunk line 50 completes a circuit for energizing the winding of the start relay R340 in the selector repeater 55, this circuit extending from the grounded line conductor C211 of the trunk line 50 by way of the set of switch springs S310, the contacts 362 and the winding of R340 to battery. When thus energized the start relay R340 operates to complete, at the contacts 341, a path for applying battery potential by way of the upper winding of the line 20 relay R325 to the line conductor C210 of the trunk line 50, thereby to complete a circuit for energizing in series the upper winding of the line relay R325 in the selector repeater 55 and the winding of the bridge relay R250 in the trunk 25 circuit 80. This circuit extends from ground by way of the contacts 233 and the winding of R250 to the contacts 221 and from ground by way of the resistor 242 and the contacts 252 to the contacts 221 and from the contacts 221 by way of the line conductor C210 of the trunk line 50, the contacts 341 and 381 and the upper winding of R325 to battery. When thus energized the bridge relay R250 in the trunk circuit 80 and the line relay R325 in the selector repeater 55 operate. 30 35 40 45 50 55 60 65 70 75

Upon operating, the bridge relay R250 interrupts, at the contacts 252, the previously traced multiple path in the above-traced circuit, including the resistor 242, and completes, at the contacts 253, an obvious circuit for energizing the winding of the hold relay R230. When thus energized the hold relay R230 operates to complete, at the contacts 234, an obvious path for applying ground potential to the control conductor C203 of the trunk 81, thereby to mark the trunk 81 in the trunk circuit 80 as busy to the non-numerical automatic switches having access thereto. Further the hold relay R230 interrupts, at the contacts 232, a further point in the previously mentioned circuit for energizing the winding of the busy relay R240 and interrupts, at the contacts 233, the previously traced circuit for energizing in series the winding of the bridge relay R250 in the trunk circuit 80 and the upper winding of the line relay R325 in the selector repeater 55, a loop circuit traced hereinafter

being completed at this time, including the winding of the bridge relay **R250** in the trunk circuit **80** and the upper and lower windings of the line relay **R325** in the selector repeater **55**. Finally the hold relay **R230** completes, at the contacts **231**, a connection between the line conductor **C202** of the trunk **81** and the line conductor **C211** of the trunk line **50**. Accordingly, at this time, the line conductor **C201** of the trunk **81** is operatively connected by way of the condenser **225** and the contacts **251** to the line conductor **C210** of the trunk line **50**; while the line conductor **C202** of the trunk **81** is operatively connected by way of the condenser **226** and the contacts **231** to the line conductor **C211** of the trunk line **50**.

Upon operating, the line relay **R325** in the selector repeater **55** completes, at the contacts **326**, the previously mentioned loop circuit for energizing in series the winding of the bridge relay **R250** in the trunk circuit **80** and the upper and lower windings of the line relay **R325** in the selector repeater **55**, this circuit extending from ground by way of the set of switch springs **S313**, the contacts **353** and **326**, the lower winding of **R325**, **C211**, the contacts **224**, the winding of **R250**, the contacts **221**, **C210**, the contacts **341** and **381** and the upper winding of **R325** to battery. Also the line relay **R325** completes, at the contacts **326**, a series holding circuit for energizing the lower winding thereof and the winding of the start relay **R340**, this circuit extending from ground by way of the set of switch springs **S313**, the contacts **353** and **326**, the lower winding of **R325**, **C211**, the set of switch springs **S310**, the contacts **362** and the winding of **R340** to battery. Further the line relay **R325** completes, at the contacts **327**, an obvious circuit for energizing the winding of the hold relay **R330**, thereby to cause the latter relay to operate. Upon operating, the hold relay **R330** completes, at the contacts **333**, an alternative loop circuit for energizing in series the winding of the bridge relay **R250** in the trunk circuit **80** and the upper and lower windings of the line relay **R325** in the selector repeater **55**; and an alternative series circuit for energizing the lower winding of the line relay **R325** and the winding of the start relay **R340**, these circuits extending from ground by way of the contacts **317** of the set of switch springs **S315**, the contacts **333** and the lower winding of **R325** to the line conductor **C211** of the trunk line **50**; and therefrom by way of the previously traced circuits to battery at the upper winding of the line relay **R325** and to battery at the winding of the start relay **R340**.

Also the hold relay **R330** completes, at the contacts **332**, a direct loop circuit for energizing in series the winding of the bridge relay **R250** in the trunk circuit **80** and the upper and lower windings of the line relay **R325** in the selector repeater **55**, this circuit extending from ground by way of the set of switch springs **S313** and the contacts **353** and **326** and from ground by way of the contacts **317** of the set of switch springs **S315** and the contacts **333**, by way of the lower winding of the line relay **R325** to the line conductor **C211** of the trunk line **50**, and therefrom by way of the previously traced path, including the winding of the bridge relay **R250** in the trunk circuit **80** to the line conductor **C210** of the trunk line **50**, and therefrom by way of the contacts **332** and the upper winding of **R325** to battery. Further the hold relay **R330** interrupts, at the contacts **334**, a point in a circuit traced hereinafter for energizing the release magnet

M309 of the switching mechanism **300** and completes, at the contacts **336**, a circuit for energizing the upper winding of the transfer relay **R380**, this circuit extending from ground by way of the contacts **336**, **342** and the upper winding of **R380** to battery. When thus energized the transfer relay **R380** operates to prepare, at the contacts **384**, a circuit traced hereinafter for energizing the vertical magnet **M305** of the switching mechanism **300** and to prepare, at the contacts **385**, a circuit traced hereinafter for energizing the winding of the rotary magnet **M307** of the switching mechanism **300**.

Further, the hold relay **R330** completes, at the contacts **336**, a path for applying ground potential to the control conductor **C454** of the trunk **35** extending between the selector repeater **55** and the operator connecting apparatus at the various operator positions, this path extending from ground by way of the contacts **336**, **343** and **355** to the control conductor **C454** of the trunk **35**. The application of ground potential to the control conductor **C454** of the trunk **35** completes obvious multiple circuits for illuminating the line lamps in the operator connecting apparatus at the various operator positions. For example, the line lamp **L447** in the operator connecting apparatus **32** at the first operator position **30** is illuminated, thereby to indicate to the operator thereat that there is a call from the distant exchange **70** on the selector repeater **55** waiting to be answered. Assuming that the call is answered at the first operator position **30**, this is accomplished by operating the connect key **K440** in the operator connecting apparatus **32** individually associated with the trunk **35**. When the connect key **K440** is thus operated there is completed, at the contacts **443** thereof, an obvious path for applying battery potential by way of the cable **480** and the resistor **448** to the control conductor **C453** of the trunk **35** and obvious multiple circuits for illuminating the answer lamps **L446**, etc., in the operator connecting apparatus **32**, etc. The illumination of the answer lamp **L446**, etc., in the operator connecting apparatus **32**, etc., indicates to the operators at the various operator positions that the connect key in one operator connecting apparatus occupies its operated position, thereby to complete a connection between the selector repeater **55** and the associated operator position.

The application of battery potential to the control conductor **C453** of the trunk **35** completes a circuit for energizing the winding of the answer relay **R350**, this circuit extending from ground by way of the contacts **336**, **343** and the winding of **R350** to battery potential upon the control conductor **C453** of the trunk **35**. When thus energized the answer relay **R350** operates to interrupt, at the contacts **355**, the previously traced circuits for illuminating the line lamps, **L447**, etc., in the operator connecting apparatus **32**, etc., thereby to indicate to the operator at the first operator position **30** that the selector repeater **55** has been conditioned to be responsive to operation of the key sender **33**, in a manner more fully explained hereinafter. Also when the connect key **K440** in the operator connecting apparatus **32** is thus operated there is completed, at the contacts **441** and **442** thereof, an obvious connection between the line conductors **C451** and **C452** of the trunk **35** and the trunk conductors **C431** and **C432** at the first operator position **30**, both the operator telephone and control equipment **31** and the key sender **33** being directly

bridged across the trunk conductors C431 and C432.

Also, upon operating, the answer relay R350 completes, at the contacts 354, a circuit for energizing the winding of the hold relay R360, this circuit extending from ground by way of the set of switch springs S313, the contacts 354 and the winding of R360 to battery. When thus energized the hold relay R360 operates to interrupt, at the contacts 362, the previously traced holding circuit for energizing in series the lower winding of the line relay R325 and the winding of the start relay R340 and to complete, at the contacts 363, an alternative holding circuit for energizing the winding of the start relay R340. The last-mentioned circuit extends from ground by way of the contacts 336, 342 and 363 and the winding of R340 to battery. Accordingly, the start relay R340 remains in its operated position. Also the line relay R325 remains in its operated position due to the completed direct loop circuit including the winding of the bridge relay R250 in the trunk circuit 80 and the upper and lower windings of the line relay R325 in the selector repeater 55. Also the hold relay R360 prepares, at the contacts 361, a circuit traced hereinafter for energizing the lower winding of the control relay R375 and prepares, at the contacts 364, a circuit traced hereinafter for energizing the winding of the impulse relay R370. Finally the answer relay R350 completes, at the contacts 352, an operative connection between the operator telephone and control equipment 31 at the first operator position 30 and the trunk line 50, this connection extending from the line conductor C210 of the trunk line 50 by way of the condenser 321, the contacts 346, the line conductor C451 of the trunk 35, the contacts 441 of the connect key K440 and the trunk conductor C431 to the operator telephone and control equipment 31; and from the line conductor C211 of the trunk line 50 by way of the condenser 322, the contacts 352, the line conductor C452 of the trunk 35, the contacts 442 of the connect key K440 and the trunk conductor C432 to the operator telephone and control equipment 31. As previously noted, the telephone instrument at the subscriber substation A is operatively connected by way of the telephone line 71, the non-numerical automatic switch 78, the trunk 81 and the trunk circuit 80 to the trunk line 50 at this time; while the trunk line 50 is operatively connected by way of the selector repeater 55, the trunk 35 and the connect key K440 to the operator telephone and control equipment 31 at this time. Accordingly, the telephone instrument at the subscriber substation A in the distant exchange 70 is operatively connected to the operator telephone and control equipment 31 at the first operator position 30 in the central exchange 20, whereupon the subscriber at the subscriber substation A and the operator at the first operator position 30 communicate with each other, the operator at the first operator position 30 being advised concerning the extension of the call.

After answering the call on the trunk line 50, the operator at the first operator position 30 may extend the call to any subscriber substation in the central exchange 20 or to any subscriber substation in the distant exchange 70. Assuming that the call is to be extended to a subscriber substation in the central exchange 20, such as the subscriber substation D, the operator at the first operator position 30 initiates the extension of the call by operating the key sender 33, there-

by to cause a number of digits to be registered in the several registers included therein and corresponding to the switch train route, including the selector repeater 55 and the local automatic switch train 21, to the telephone line 42 extending to the subscriber substation D. More particularly, the first digit is registered in the first register 400 in the key sender 33; whereupon the register switch S410 therein is operated away from its normal position and the digit switch S420 therein is set such that it is operated away from its normal position when a predetermined number of impulses corresponding to the digit registered in the first register 400 have been transmitted over the trunk 35 to the selector repeater 55. Similarly, the second, third, etc., digits are registered in the second, third, etc., registers in the key sender 33. When the register switch S410 in the first register 400 in the key sender 33 is operated away from its normal position, there is completed a path for applying ground potential in the first register 400 to the line conductor C452 of the trunk 35, this path extending from ground by way of the contacts 424 of the digit switch S420 in the first register 400, the contacts 412 of the register switch S410 in the first register 400, the trunk conductor C432 and the contacts 442 of the connect key K440 to the line conductor C452 of the trunk 35. This application of ground potential to the line conductor C452 of the trunk 35 completes an obvious circuit for energizing the winding of the send relay R345 in the selector repeater 55, thereby to cause operation of the send relay R345. Upon operating, the send relay R345 completes, at the contacts 348, an obvious holding circuit for energizing the winding of the answer relay R350 and completes, at the contacts 347, the previously mentioned circuit for energizing the lower winding of the control relay R375. The circuit for energizing the lower winding of the control relay R375 extends from ground by way of the contacts 347, 361, 371 and 308 and the lower winding of R375 to battery. When thus energized the control relay R375 operates to complete, at the contacts 376, a holding circuit for energizing the lower winding thereof, this circuit extending from ground by way of the contacts 347, 376 and 308 and the lower winding of R375 to battery. Further the control relay R375 completes, at the contacts 377, a circuit for energizing in series the winding of the impulse relay R370 in the selector repeater 55 and the register magnet M425 in the first register 400 in the key sender 33, this circuit extending from ground by way of the contacts 371 and 364, the winding of R370, the contacts 391, the line conductor C451 of the trunk 35, the contacts 441 of the connect key K440, the trunk conductor C431, the contacts 411 of the register switch S410 in the first register 400, the contacts 421 of the digit switch S420 in the first register 400 and the winding of M425 to battery. When this circuit is completed the impulse relay R370 and the register magnet M425 operate.

Upon operating, the register magnet M425 in the first register 400 operates the associated pawl 426, thereby to condition the associated ratchet wheel 427 to be driven one step in the clockwise direction. Upon operating, the impulse relay R370 completes, at the contacts 373, an obvious holding circuit for energizing the winding of the hold relay R360 and completes, at the contacts 372, a circuit for energizing the vertical magnet M305, this circuit extending from ground by

way of the contacts 347, 376, 372 and 384 and the vertical magnet M305 to battery. When thus energized the vertical magnet M305 operates to drive the wiper set of the switching mechanism 300 one step in the vertical direction and to complete, at the contacts 306, a circuit for energizing the upper winding of the control relay R375, this circuit extending from ground by way of the contacts 347, 376 and 306 and the upper winding of R375 to battery. When both the upper winding and the lower winding of the control relay R375 are thus energized this relay restores, the control relay R375 being of the differential type. Upon restoring, the control relay R375 interrupts, at the contacts 371, the previously traced series circuit for energizing the winding of the impulse relay R370 in the selector repeater 55 and the register magnet M425 in the first register 400, thereby to cause the impulse relay R370 and the register magnet M425 to restore.

Upon restoring, the register magnet M425 in the first register 400 releases the associated pawl 426, thereby to cause the pawl 426 to drive the associated ratchet wheel 427 one step in the clockwise direction, thereby to effect registration of one impulse in the first register 400. Upon restoring the impulse relay R370 interrupts, at the contacts 372, the previously traced circuit for energizing the vertical magnet M305, thereby to cause the vertical magnet to restore. Upon restoring, the vertical magnet M305 interrupts, at the contacts 306, the previously traced circuit for energizing the upper winding of the control relay R375. Also, upon restoring, the control relay R375 interrupts, at the contacts 376, the previously traced holding circuit for energizing the lower winding thereof. Finally, upon restoring, the impulse relay R370 recompletes, at the contacts 371, the previously traced original circuit for energizing the lower winding of the control relay R375.

Accordingly, the control relay R375 reoperates, thereby to recomplete, at the contacts 371, the previously traced series circuit for energizing the winding of the impulse relay R370 in the selector repeater 55 and the register magnet M425 in the first register 400 in the key sender 33, whereupon the impulse relay R370 and the register magnet M425 reoperate. Upon reoperating, the control relay R375 recompletes, at the contacts 376, the previously traced holding circuit for energizing the lower winding thereof; and upon operating, the impulse relay R370 recompletes, at the contacts 372, the previously traced circuit for energizing the vertical magnet M305, thereby to cause the vertical magnet M305 to reoperate. Upon reoperating, the vertical magnet M305 recompletes, at the contacts 306, the previously traced circuit for energizing the upper winding of the control relay R375, thereby to cause the latter relay to restore.

Accordingly, the impulse relay R370, the control relay R375 and the vertical magnet M305 interact in the above-described manner, thereby to cause the vertical magnet M305 to drive the wiper set of the switching mechanism 300 step by step in the vertical direction and to cause the register magnet M425 to drive the associated ratchet wheel 427 step by step in the clockwise direction. When the wiper set of the switching mechanism 300 has been driven in the vertical direction a number of steps corresponding to the impulses of the digit registered in the first register 400 in the key sender 33, the ratchet

wheel 427 is driven a corresponding number of steps in the clockwise direction, thereby to cause the digit switch S420 in the first register 400 to be operated away from its normal position. 5 When the digit switch S420 in the first register 400 is operated away from its normal position there is completed, at the contacts 423 thereof, a path substantially identical to that previously traced for applying ground potential in the second register by way of the control conductor C476 extending thereto to the line conductor C452 of the trunk 35, thereby to retain completed the previously mentioned circuit for energizing the winding of the send relay R345 in the selector repeater 55. Also, at the contacts 424 of the register switch S420 in the first register 400, there is interrupted the previously traced path for applying ground potential in the first register 400 to the line conductor C452 of the trunk 35. Accordingly, the send relay R345 in the selector repeater 55 remains in its operated position at this time. Further, at the contacts 421 of the register switch S420 in the first register 400, there is interrupted the previously traced path for applying battery potential by way of the register magnet M425 in the first register 400 to the line conductor C451 of the trunk 35; and there is prepared, at the contacts 422 of the register switch S420 in the first register 400, a path substantially identical to that previously traced for applying battery potential by way of the register magnet in the second register in the key sender 33 and the control conductor C475 extending thereto to the line conductor C451 of the trunk 35. At this point it is noted that there is a delay in the application of battery potential by way of the register magnet in the second register in the key sender 33 to the control conductor C475 and consequently to the line conductor C451 of the trunk 35. Accordingly, when the control relay R375 reoperates incident to the restoration of the impulse relay R370 and the vertical magnet M305, the impulse relay R370 does not immediately operate as the previously mentioned circuit for energizing in series the winding of the impulse relay R370 and the register magnet in the second register in the key sender 33 is not immediately completed. This delay is produced in the second register in the key sender 33 in order to allow the switching mechanism 300 in the selector repeater 55 adequate time to operate automatically and seize an idle trunk in the previously selected group of trunks, in a manner more fully explained subsequently. 55 At this point it is noted that, when the wiper set of the switching mechanism 300 is driven one step in the vertical direction, the sets of switch springs S310 and S313 are actuated into disengagement and the sets of switch springs S311 and S312 are actuated into engagement. When the set of switch springs S311 is actuated into engagement, a path traced hereinafter is prepared for applying ground potential to the line conductor C210 of the trunk line 50; and when the set of switch springs S312 is actuated into engagement, a further point in the previously mentioned circuit for energizing the release magnet M309 is prepared. When the set of switch springs S310 is actuated into disengagement, a further point in the previously traced original circuit for energizing the winding of the start relay R340 is interrupted, the start relay R340 being retained in its operated position at this time due to the completed holding circuit for en-

ergizing the winding thereof under the control of the operated hold relay R360. When the set of switch springs S313 is actuated into disengagement the previously traced original circuit for energizing the winding of the hold relay R360 is interrupted, the hold relay R360 being retained in its operated position at this time due to the intermittent completion of the previously traced holding circuit for energizing the winding thereof under the control of the impulse relay R370, the hold relay R360 being of the slow-to-release type. Accordingly, the start relay R340 remains in its operated position, while the hold relay R360 remains in its operated position as long as the impulse relay R370 is intermittently operated. However, after the digit switch S420 in the first register 400 in the key sender 33 is operated as previously explained, battery potential is not immediately connected in the second register in the key sender 33 to the line conductor C451 of the trunk 35. Accordingly, the impulse relay R370 remains in its restored position following the complete operation of the wiper set of the switching mechanism 300 in the vertical direction. Hence, shortly after the impulse relay R370 restores to interrupt, at the contacts 373, the previously mentioned holding circuit for energizing the winding of the hold relay R360, the latter relay restores. Upon restoring, the hold relay R360 interrupts, at the contacts 363, the previously traced holding circuit for energizing the winding of the start relay R340, thereby to cause the latter relay to restore shortly thereafter, the start relay R340 being of the slow-to-release type. Upon restoring, the start relay R340 interrupts, at the contacts 341, the original loop circuit for energizing in series the winding of the bridge relay R250 in the trunk circuit 80 and the upper and lower windings of the line relay R325 in the selector repeater 55; however, the last-mentioned relays do not restore at this time due to the previously traced completed alternative loop circuit for energizing the windings thereof. Further the start relay R340 interrupts, at the contacts 342, a further point in the previously traced holding circuit for energizing the winding thereof and interrupts, at the contacts 342, the previously traced circuit for energizing the upper winding of the transfer relay R380. However, the transfer relay R380 does not immediately restore, this relay being of the slow-to-release type. Also the start relay R340 interrupts, at the contacts 343, the previously traced original circuit for energizing the winding of the answer relay R350, the latter relay remaining in its operated position at this time due to the completed holding circuit for energizing the winding thereof. Finally, the start relay R340 prepares, at the contacts 344, a test circuit traced hereinafter for energizing the winding of the switching relay R390.

Also, upon restoring, the hold relay R360 interrupts, at the contacts 364, a further point in the previously traced circuit for energizing the winding of the impulse relay R370 and completes, at the contacts 365, a holding circuit for energizing the lower winding of the transfer relay R380 and a circuit for energizing the rotary magnet M307, the control relay R375 occupying its operated position at this time. These circuits extend from ground by way of the contacts 371 and 365 to the contacts 385 and from the contacts 385 by way of the lower winding of R380 to battery, and from the contacts 385 by way of the rotary magnet M307 to battery. When the lower winding of the transfer relay R380 is thus energized

this relay remains in its operated position; and when the rotary magnet M307 is thus energized it operates to drive the wiper set of the switching mechanism 300 one step in the rotary direction and to interrupt, at the contacts 308, the previously traced circuit for energizing the lower winding of the control relay R375, thereby to cause the latter relay to restore. Upon restoring, the control relay R375 interrupts, at the contacts 377, the previously traced holding circuit for energizing the lower winding of the transfer relay R380 and the previously traced circuit for energizing the rotary magnet M307. When these circuits are interrupted the transfer relay R380 remains in its operated position, this relay being of the slow-to-release type; while the rotary magnet M307 restores to recomplete, at the contacts 308, a test connection between the control wiper 303 of the wiper set of the switching mechanism 300 and the lower winding of the control relay R375.

At this time, the wiper set of the switching mechanism 300 engages the contact set in the associated contact bank terminating the first trunk in the associated group of trunks extending to the local automatic switch train 21. In the event the first trunk mentioned is busy, ground potential appears upon the control conductor thereof, thereby to complete a circuit for energizing the lower winding of the control relay R375 and a path for short-circuiting the winding of the switching relay R390. The circuit for energizing the lower winding of the control relay R375 extends from the grounded control conductor of the trunk mentioned by way of the control wiper 303, the contacts 394, 382 and 308 and the lower winding of R375 to battery; while the path for short-circuiting the winding of the switching relay R390 extends from the grounded control wiper 303 by way of the contacts 394 and 382, the winding of R390, the contacts 319 of the set of switch springs S318, the contacts 344 and 336 to ground. Accordingly, in the event the trunk mentioned is busy, the control relay R375 reoperates while the switching relay R390 remains in its restored position. Upon reoperating, the control relay R375 recompletes, at the contacts 371, the previously traced holding circuit for energizing the lower winding of the transfer relay R380 and the previously traced circuit for energizing the rotary magnet M307, thereby to retain the transfer relay R380 in its operated position and to cause reoperation of the rotary magnet M307. Accordingly, the control relay R375 and the rotary magnet M307 interact in the manner described above, thereby to cause the wiper set of the switching mechanism 300 to be driven step by step in the rotary direction until it selects an idle trunk in the group of trunks extending to the local automatic switch train 21.

When an idle trunk in the group of trunks extending to the local automatic switch train 21 is thus selected, further operation of the rotary magnet M307 is arrested due to the absence of ground potential upon the control conductor thereof. More particularly, when no ground potential is applied to the control wiper 303 the previously traced circuit for energizing the lower winding of the control relay R375 is not recompleted and the previously traced path for short-circuiting the winding of the switching relay R390 is interrupted. Hence, at this time, a circuit is completed for energizing in series the lower winding of the control relay R375 and the

winding of the switching relay R390, this circuit extending from ground by way of the contacts 336 and 344, the contacts 319 of the set of switch springs S318, the windings of R390, the contacts 308 and the lower winding of R375 to battery. When this series circuit is completed the switching relay R390 operates; however, the control relay R375 does not reoperate due to the high series resistance of this circuit. Upon operating, the switching relay R390 completes, at the contacts 395 and 396, obvious paths for applying ground potential to the control wipers 303 and 304, respectively, thereby to cause ground potential to be applied to the two control conductors of the selected trunk in the group of trunks extending to the local switch train 21, such as the trunk 36. Also, upon operating, the switching relay R390 interrupts, at the contacts 391, a further point in the previously traced circuit for energizing the winding of the impulse relay R370, and prepares, at the contacts 392 and 393, operative connections between the line conductors C210 and C211 of the trunk line 50 and the line conductors C471 and C472, respectively, of the trunk 36. Finally, the switching relay R390 completes, at the contacts 392, an operative connection between the line conductors C471 of the trunk 36 extending to the local automatic switch train 21 and the line conductor C451 of the trunk 35 extending to the key sender 33, for a purpose more fully explained hereinafter. Shortly following the operation of the control relay R375 the transfer relay R380 restores, thereby to interrupt, at the contacts 385, a further point in the previously traced holding circuit for energizing the lower winding of the transfer relay R380 and a further point in the previously traced circuit for energizing the rotary magnet M307.

Accordingly, at this time, the selector repeater 55 has operated in response to the first digit registered in the first register 400 in the key sender 33 to select a group of trunks extending to the local automatic switch train 21 and has then operated automatically to select the idle trunk 36 in the previously mentioned group of trunks extending to the local automatic switch train 21. When ground potential is applied to the control conductors C473 and C474 of the trunk 36, the local automatic switch train 21 is rendered responsive to additional digits registered in the additional registers in the key sender 33 to operate subsequently. Shortly following the complete operation of the selector repeater 55 the second register in the key sender 33 operates, thereby to cause battery potential to be applied by way of the register magnet therein to the control conductor C475 extending thereto and, accordingly, by way of the previously traced circuit to the line conductor C451 of the trunk 35. The application of battery potential to the line conductor C451 of the trunk 35 completes an obvious path, including the line wiper 301 of the wiper set of the switching mechanism 300, for applying battery potential to the line conductor C471 of the trunk 36 extending to the local automatic switch train 21. This application of battery potential to the line conductor C471 of the trunk 36 initiates operation of the local automatic switch train 21 whereupon the local automatic switch train 21 responds to the digit registered in the second register in the key sender 33 and causes revertive impulses to be returned to the second register in the key sender 33, thereby to control the transfer of the circuit from the second register to the third register in the key

75 sender 33, in a manner similar to the transfer of the connection from the first register 400 to the second register in the key sender 33, previously explained. Accordingly, the local automatic switch train 21 operates in accordance with the second, third, etc., digits registered in the second, third, etc., registers in the key sender 33, thereby to seize the telephone line 42 extending to the subscriber substation D. The subsequent operation of the local automatic switch train 21 depends upon the idle or busy condition of the telephone line 42, in a manner more fully explained hereinafter.

15 After all of the digits registered in the various registers in the key sender 33 have been transmitted by way of the trunk 35, the selector repeater 55 and the trunk 36 to the local automatic switch train 21 in order to cause operation thereof to seize the telephone line 42 extending to the subscriber substation D in the manner previously explained, the last register in the key sender 33 operates, thereby to cause ground and battery potential to be removed from the line conductors C452 and C451, respectively, of the trunk 35. When battery potential is removed from the line conductor C451 of the trunk 35, further operation of the local automatic switch train 21 is arrested; and when ground potential is removed from the line conductor C452 of the trunk 35 the previously traced circuit for energizing the winding of the send relay R345 is interrupted, thereby to cause the latter relay to restore. Upon restoring, the send relay R345 completes, at the contacts 346, a connection 20 traced hereinafter between the line conductor C210 of the trunk line 50 and the line conductor C471 of the trunk 36, and interrupts, at the contacts 348, the previously traced holding circuit for energizing the winding of the answer relay 25 R350, thereby to cause the latter relay to restore and complete, at the contacts 351, a connection between the line conductor C211 of the trunk line 50 and the line conductor C472 of the trunk 36. At this time, the line conductor C210 of the trunk line 50 is connected by way of the condenser 321, the contacts 346 and 392 and the line wiper 301 to the line conductor C471 of the trunk 36; and the line conductor C211 of the trunk line 50 is connected by way of the condenser 322, the contacts 351 and 393 and the line wiper 302 to the line conductor C472 of the trunk 36; the trunk line 50 being connected by way of the trunk circuit 80, the trunk 81, the non-numerical automatic switch 78 and the telephone line 71 to the subscriber sub-station A in the distant exchange 70 and the trunk 36 being connected to the local automatic switch train 21. Also, when the previously traced holding circuit for energizing the winding of the answer relay 30 R350 is interrupted, at the contacts 348, due to the restoration of the send relay R345, the resistor 448 included in the previously traced circuit for illuminating the answer lamp L446 in the operator connecting apparatus 32 at the first operator position 30 is unloaded somewhat, thereby to cause the answer lamp L446 to be illuminated more brightly. When the answer lamp L446 is thus illuminated more brightly, it indicates to the operator at the first operator position 35 that the key sender 33 has been released. The operator at the operator position 30 then returns the connect key K440 in the operating connecting apparatus 32 to its normal position, thereby to interrupt, at the contacts 441 and 442 thereof, the connection between both the operator telephone

and control equipment 31 and the key sender 33 and the trunk 35 extending to the selector repeater 55 and to render the first operator position 30 again idle. Also when the connect key K440 is returned to its normal position there is interrupted, at the contacts 443 thereof, the previously traced multiple circuits for illuminating the answer lamps L446, etc., included in the operator connecting apparatus 32, etc., at the various operator positions, thereby to indicate to the operator at the first operator position 30 that the apparatus thereat is idle and available for use in answering another call.

In the event the called subscriber substation D in the central exchange 20 is busy at this time, the local automatic switch train 21 operates to return busy tone current over the previously traced connection to the subscriber substation A in the distant exchange 70, thereby to indicate to the subscriber thereat that the connection cannot be immediately completed due to the busy condition of the called subscriber substation D. On the other hand, in the event the called subscriber substation D is idle at this time, the local automatic switch train 21 operates to cause ringing current to be projected over the telephone line 42 to the called subscriber substation D and to cause ring-back tone current to be returned over the previously traced connection to the calling subscriber substation A, thereby to indicate to the subscriber at the subscriber substation A that the called subscriber substation D in the central exchange 20 is being rung. Also when the local automatic switch train 21 seizes the telephone line 42 extending to the called subscriber substation D, the line circuit 46 individually associated therewith operates, thereby to mark the telephone line 42 as busy to the switches in the local automatic switch train 21 having access thereto. When the subscriber at the called subscriber substation D answers the call the local automatic switch train 21 switches through, thereby to complete a connection between the trunk 36 and the telephone line 42, in order to complete an established connection between the calling subscriber substation A in the distant exchange 70 and the called subscriber substation D in the central exchange 20.

In the foregoing explanation of the mode of operation of the selector repeater 55 it was assumed that there was an idle trunk in the previously selected group of trunks extending to the local automatic switch train 21 and that the selector repeater 55 seized the idle trunk in this group of trunks incident to the operation of the switching mechanism 300 thereof in the rotary direction. However, it may occur that there are no idle trunks in the previously selected group of idle trunks extending to the local automatic switch train 21; in which event the control relay R375 and the rotary magnet M307 continue to operate in the manner previously explained, in order to drive the wiper set of the mechanism 300 step by step in the rotary direction until the wiper set is driven eleven steps away from its normal position. When the wiper set of the switching mechanism 300 is driven eleven steps away from its normal position the sets of switch springs S315 and S318 are operated. More particularly, the contacts 319 of the set of switch springs S318 are actuated into disengagement; while the contacts 320 of the set of switch springs S318 are actuated into engagement, thereby to complete an alternative holding circuit for energizing the winding of the hold relay R360. This circuit extends from

ground by way of the contacts 336 and 344, the contacts 320 of the set of switch springs S318 and the winding of R360 to battery. When thus energized the hold relay R360 operates and completes, at the contacts 361, the previously traced circuit for energizing the lower winding of the control relay R375, thereby to cause the latter relay to operate. Upon operating, the control relay R375 completes, at the contacts 371, the previously traced series circuit for energizing the winding of the impulse relay R370 in the selector repeater 55 and the winding of the register magnet in the second register in the key sender 33, thereby to cause the impulse relay R370 and the register magnet mentioned to operate. Also upon operating, the control relay R375 completes, at the contacts 376, the previously traced holding circuit for energizing the lower winding thereof. Upon operating, the impulse relay R370 completes, at the contacts 372, an alternative circuit for energizing the upper winding of the control relay R375, this circuit extending from ground by way of the contacts 347, 376, 372 and 383 and the upper winding of R375 to battery. When both the upper winding and the lower winding of the control relay R375 are thus energized, this relay restores as it is of the differential type, as previously noted. Upon restoring, the control relay R375 interrupts, at the contacts 376, the previously traced holding circuit for energizing the lower winding thereof and interrupts, at the contacts 371, the previously traced circuit for energizing the winding of the impulse relay R370, thereby to cause the latter relay to restore. Upon restoring, the impulse relay R370 interrupts, at the contacts 372, the previously traced alternative circuit for energizing the upper winding of the control relay R375 and recompletes, at the contacts 371, the previously traced original circuit for energizing the lower winding of the control relay R375. Accordingly, the impulse relay R370 and the control relay R375 interact in the above-described manner in order to cause all the digits registered in the second, third, etc., registers in the key sender 33 to be transmitted, whereby the registers mentioned in the key sender 33 are completely cleared, in the manner previously described, the same as though the selector repeater 55 had switched through to seize the local automatic switch train 21 in the manner previously explained.

When the set of switch springs S315 is thus actuated the previously traced alternative loop circuit, including the winding of the bridge relay R250 in the trunk circuit 80 and the upper and lower windings of the line relay R325 in the selector repeater 55, is interrupted at the contacts 317 thereof; and, at the contacts 316 of the set of switch springs S315, there is completed a further loop circuit including the winding of the bridge relay R250 in the trunk circuit 80 and the upper and lower windings of the line relay R325 in the selector repeater 55. This further loop circuit extends from ground by way of the winding of a busy tone transformer, not shown, the set of switch springs S314, the contacts 316 of the set of switch springs S315, the contacts 333, the lower winding of R325, C211, the contacts 224, the winding of R250, the contacts 221, C210, the contacts 332 and the upper winding of R325 to battery. Accordingly, busy tone current traverses the previously traced further loop circuit, thereby to cause busy tone current to be projected from the trunk circuit 80 over the trunk 81, the

non-numerical automatic switch 78 and the telephone line 71 to the subscriber substation A in the distant exchange 70 in order to cause the receiver of the telephone instrument at the subscriber substation A to produce busy tone. The subscriber at the calling subscriber substation A then effects the release of the selector repeater 55 by replacing the receiver of the telephone instrument at the subscriber substation A upon its associated switchhook.

At this point it is noted that the release of the selector repeater 55, in the event it fails to find an idle trunk in the previously selected group of trunks extending to the local automatic switch train 21, in the manner described above, and the release of the established connection between the calling subscriber substation A in the distant exchange 70 and the called subscriber substation D in the central exchange 20 are performed in an identical manner under the control of the subscriber at the calling subscriber substation A. More particularly, when the subscriber at the calling subscriber substation A in the distant exchange 70 replaces the receiver of the telephone instrument thereat upon its associated switchhook the loop circuit between the line relay R220 in the trunk circuit 80 and the subscriber substation A is interrupted, thereby to cause the latter relay to restore; also the line circuit 75 individually associated with the telephone line 71 extending to the subscriber substation A is controlled, thereby to initiate operation of the non-numerical automatic switch 78 individually associated with the telephone line 71 extending to the subscriber substation A. More particularly, the non-numerical automatic switch 78 is operated to its normal position, whereupon the line circuit 75 is controlled, thereby to mark the telephone line 71 extending to the subscriber substation A as idle to the switches having access thereto.

Upon restoring, the line relay R220 interrupts, at the contacts 224, the previously traced series loop circuit, including the winding of the bridge relays R250 in the trunk circuit 80, and the upper and lower windings of the line relay R325 in the selector repeater 55, thereby to cause the latter relays to restore. Upon restoring, the bridge relay R250 interrupts, at the contacts 253, the previously mentioned circuit for energizing the winding of the hold relay R230, thereby to cause the latter relay to restore shortly thereafter, the hold relay R230 being of the slow-to-release type. Upon restoring, the hold relay R230 interrupts, at the contacts 234, the previously mentioned path for applying ground potential to the control conductor C203 of the trunk 21, thereby to mark the trunk 21 and the trunk circuit 80 as idle to the non-numerical automatic switches having access thereto. Upon restoring, the line relay R325 interrupts, at the contacts 327, the previously mentioned circuit for energizing the winding of the hold relay R330, thereby to cause the latter relay to restore shortly thereafter, the hold relay R330 being of the slow-to-release type. Upon restoring, the hold relay R330 completes, at the contacts 334, the previously mentioned circuit for energizing the release magnet M309, this circuit extending from ground by way of the contacts 334, the set of switch springs S312 and the release magnet M309 to battery. When thus energized the release magnet M309 operates, thereby to release the wiper set of the switching mechanism 300 in

order to cause this wiper set to be returned to its normal position. When the wiper set of the switching mechanism 300 is returned to its normal position, the sets of switch springs S310 and S313 are actuated into engagement; the sets of switch springs S311 and S312 are actuated into disengagement; while the sets of switch springs S315 and S318 are actuated only in the event they have been previously actuated due to the failure of the selector repeater 55 to seize an idle trunk in the previously selected group of trunks extending to the local automatic switch train 21.

Assuming that the present release is effected incident to the failure of the selector repeater 55 to seize a trunk in the previously selected group of trunks extending to the local automatic switch train 21, the contacts 316 and 317 of the set of switch springs S315 are respectively actuated into disengagement and into engagement; while the contacts 319 and 320 of the set of switch springs S318 are actuated respectively into engagement and disengagement. Also upon restoring, the hold relay R330 interrupts, at the contacts 333, a further point in the previously traced path for projecting busy tone current over the trunk line 50 and interrupts, at the contacts 336, the previously traced alternative holding circuit for energizing the winding of the hold relay R360. At this point it is noted that the hold relay R360 does not immediately restore, this relay being of the slow-to-release type, and is retained in its operated position as long as the impulse relay R370 and the control relay R375 are interacting, in the manner previously explained, thereby to clear the various registers in the key sender 33; also until the registers in the key sender 33 are cleared the send relay R345 and the answer relay R350 remain in their operated positions. After the registers in the key sender 33 have been cleared, the previously traced circuit for energizing the send relay R345 is interrupted, thereby to cause the latter relay to restore and interrupt, at the contacts 348, the previously traced circuit for energizing the answer relay R350, whereupon the latter relay restores as previously explained. Also upon restoring, the send relay R345 interrupts, at the contacts 347, the previously traced circuit for energizing the lower winding of the control relay R375, thereby to cause the latter relay to restore and interrupt, at the contacts 377, a further point in the previously traced circuit for energizing the winding of the impulse relay R370, whereby both the control relay R375 and the impulse relay R370 occupy their restored positions. Shortly after the impulse relay R370 restores to interrupt, at the contacts 373, the previously mentioned alternative holding circuit for energizing the winding of the hold relay R360, the hold relay R360, being of the slow-to-release type, restores. At this time, the selector repeater 55 is completely released and available for further use.

On the other hand, assuming that the present release is effected subsequent to the establishment of the completed connection between the calling subscriber substation A in the distant exchange 70 and the called subscriber substation D in the central exchange 20, the release of the line relay R325 and the hold relay R330 in the selector repeater 55 are effective to cause operation of the release magnet M309, thereby to cause the wiper set of the switching mechanism 300 to be released and returned to its normal position, in the manner previously explained. Also the sets of switch springs S310, S313 and S311, S312 are respec-

tively actuated into engagement and disengagement, as previously explained. Further in the present release, the hold relay R330 interrupts, at the contacts 336, the previously traced circuit for energizing the winding of the switching relay R390 in series with the lower winding of the control relay R375, thereby to cause the switching relay R390 to restore. Upon restoring, the switching relay R390 interrupts, at the contacts 392 and 393, the previously traced connection between the selector repeater 55 and the trunk 36 extending to the local automatic switch train 21 and interrupts, at the contacts 395, the previously traced path for applying ground potential to the control conductor C473 of the trunk 36, the path for applying ground potential to the control conductor C474 of the trunk 36 being interrupted at the contacts 327 incident to the restoration of the line relay R325. At this time, the selector repeater 55 is completely released and available for further use. When ground potential is removed from the control conductors C473 and C474 of the trunk 36 extending to the local automatic switch train 21, the local automatic switch train 21 is released and rendered available for further use. At this time, when the local automatic switch train 21 is released the line circuit 46 individually associated with the telephone line 42 extending to the called subscriber substation D in the central exchange 20 is controlled, thereby to mark the telephone line 42 as idle to the switches in the local automatic switch train 21 having access thereto in the event the subscriber at the called subscriber substation D has replaced the receiver of the telephone instrument thereat upon its associated switchhook at this time, or to lock the telephone line 42 out of service in the event the subscriber at the called subscriber substation D has not replaced the receiver of the telephone instrument thereat upon its associated switchhook at this time.

In connection with the release of the selector repeater 55 it is noted that, in the event the wiper set of the switching mechanism 300 is not completely released and actually returned to its normal position incident to the restoration of the hold relay R330, a path is completed, at the contacts 331, to the restoration of the hold relay R330 to apply ground potential to the line conductor C210 of the trunk line 50, this path extending from ground by way of the set of switch springs S311 and the contacts 331 to the line conductor C210 of the trunk line 50. Accordingly, ground potential is retained upon the line conductor C210 of the trunk line 50 until the wiper set of the switching mechanism 300 is actually returned to its normal position, thereby to actuate the set of switch springs S311 into disengagement. The application of ground potential to the line conductor C210 completes a circuit for energizing the winding of the busy relay R240 in the trunk circuit 80, this circuit extending from the grounded line conductor C210 of the trunk line 50 by way of the contacts 223 and 232 and the winding of R240 to battery. When thus energized, the busy relay R240 operates to complete, at the contacts 241, an obvious path for applying ground potential to the control conductor C203 of the trunk 81, thereby to mark the trunk 81 and the trunk circuit 80 and, consequently, the trunk line 50 and the selector repeater 55 as busy to the non-numerical automatic switches having access to the trunk 81. It is noted that when the wiper set of the

switching mechanism 300 in the selector repeater 55 is completely released and returned to its normal position, the set of switch springs S311 is actuated into disengagement, thereby to interrupt the previously traced circuit for energizing the winding of the busy relay R240. The busy relay R240 then restores, thereby to interrupt, at the contacts 241, the previously mentioned path for applying ground potential to the control conductor C203 of the trunk 81 in order to mark the trunk 81 as idle to the non-numerical automatic switches having access thereto.

At this point it is noted that the call initiated at the calling subscriber substation A in the distant exchange 70 and routed therefrom by way of the telephone line 71, the non-numerical automatic switch 78, the trunk 81, the trunk circuit 80, the trunk line 50, the selector repeater 55 and the trunk 35 to the first operator position 30 and answered at the first operator position 30 by operating the connect key K440 in the operator connecting apparatus 32, may be completed to another subscriber substation in the distant exchange 70 instead of to the subscriber substation D in the central exchange 20, in the manner previously explained. The operation of the apparatus in the central exchange 20 to extend a call answered at the first operator position 30 to a subscriber substation in the distant exchange 70 is described more fully hereinafter.

Also it is noted that the call on the telephone line 71 and routed by way of the previously traced piece of apparatus to the first operator position 30 and answered thereat may have been initiated on the telephone line 71 due to the presence of a fault thereon. In other words, the call on the telephone line 71 answered at the first operator position 30 may be a false call. After the operator at the first operator position 30 detects that the call routed thereto by way of the selector repeater 55 and the trunk 35 is a false call, she operates the key sender 33, thereby to cause a single predetermined digit to be registered in the first register 400 therein. After the single digit is registered in the first register 400 in the key sender 33, operation of the selector repeater 55 is initiated, thereby to cause the wiper set of the switching mechanism 300 to be driven in the vertical direction a corresponding number of steps, in the manner previously explained. The wiper set of the switching mechanism 300 is then driven step by step in the rotary direction until it is driven eleven steps away from its normal position, this level in the associated contact bank terminating no trunks. When the wiper set of the switching mechanism 300 is thus operated in the vertical direction the set of switch springs S314 is actuated into disengagement; and when the wiper set of the switching mechanism 300 is thus operated in the rotary direction the sets of switch springs S315 and S318 are actuated, the sets of switch springs S310, S313 and S311, S312 being respectively actuated into disengagement and engagement at this time, as previously explained. More particularly, the contacts 320 of the set of switch springs S318 are actuated into engagement, thereby to complete the previously traced alternative holding circuit for energizing the winding of the hold relay R360. When thus energized the hold relay R360 operates, thereby to condition the impulse relay R370 and the control relay R375 for operation in order to insure that the various registers in the key sender 33 are cleared. Also the contacts 317 of the set of switch springs S315 are actuated into dis-

engagement, thereby to interrupt the previously traced alternative loop circuit, including the winding of the bridge relay R250 in the trunk circuit 80 and the upper and lower windings of the line relay R325 in the selector repeater 55. When this alternative loop circuit is thus interrupted the bridge relay R250 and the line relay R325 restore. Upon restoring, the line relay R325 interrupts, at the contacts 327, the previously traced circuit for energizing the winding of the hold relay R330, thereby to cause the latter relay to restore, as previously explained. Upon restoring, the relay R330 effects the release of the wiper set of the switching mechanism 300, in the manner previously explained. Also upon restoring, the hold relay R330 causes the hold relay R360 to restore, as previously explained. Further it is noted that, when the registers in the key sender 33 are cleared, the send relay R345 and the answer relay R350 restore, as previously noted. Finally, the sets of switch springs S310, S311, S312, S313, S315 and S318 are actuated back to their normal positions when the wiper set of the switching mechanism 300 is returned to its normal position, in the manner previously explained. Accordingly, at this time, the selector repeater 55 is completely released.

Upon restoring, the bridge relay R250 in the trunk circuit 80 interrupts, at the contacts 253, the previously mentioned circuit for energizing the winding of the hold relay R230, thereby to cause the latter relay to restore and interrupt, at the contacts 234, the previously traced path for applying ground potential to the control conductor C203 of the trunk 81. At this time, when ground potential is removed from the control conductor C203 of the trunk 81, while the non-numerical automatic switch 78 is operated to seize the trunk 81, the line circuit 75 individually associated with the telephone line 71 extending to the calling subscriber substation A is operated, thereby to lock the telephone line 71 out of service until the fault has been removed therefrom and to cause the non-numerical automatic switch 78 to be operated to its normal position. At this time, the telephone line 71 extending to the calling subscriber substation A is locked out of service, while the trunk 81 is marked as idle to the non-numerical automatic switches having access thereto.

After a call has been answered at the first operator position 30 in the central exchange 20 it may be completed to any subscriber substation in the distant exchange 70, the call having originated at a subscriber substation in the distant exchange 70 or at a subscriber substation in the central exchange 20. For example, the call originating at the subscriber substation A in the distant exchange 70 and routed by way of the previously traced connection to the first operator position 30 may be extended to the subscriber substation B in the distant exchange 70 after it has been answered at the first operator position 30, in a manner previously explained. Similarly, a call originating at a subscriber substation such, for example, as the subscriber substation C in the central exchange 20, may be routed to the first operator position 30 and, after it has been answered thereat, it may be extended to the subscriber substation B in the distant exchange 70. For example, a call is initiated at the subscriber substation C in the central exchange 20 when the subscriber thereat removes the telephone instrument at the subscriber substation C from its associated switchhook,

thereby to cause the line circuit 45 individually associated with the telephone line 41 extending to the subscriber substation C to operate. Upon operating, the line circuit 45 causes the local automatic switch train 21 to seize the telephone line 41 and then to mark the telephone line 41 as busy to the switches in the local automatic switch train 21 having access thereto. The local automatic switch train 21 then operates to seize an idle trunk in the group of trunks, such as the trunk 34, extending from the local automatic switch train 21 to the operator connecting apparatus 32, etc., at the various operator positions. The operator at the first operator position 30 then answers the call by operating the connect key K445 in the operator connecting apparatus 32 individually associated with the trunk 34 and communicates with the subscriber at the calling subscriber substation C, in the manner previously explained. In order to extend the call from the first operator position 30 by way of the local automatic switch train 21 to the distant exchange 70, the operator at the first operator position 30 operates the key sender 33, thereby to cause a predetermined number of digits corresponding to the switch train routed to the called subscriber substation B in the distant exchange 70 to be registered in the various registers therein. The key sender 33 then operates to cause one or more of the digits registered in one or more of the registers therein to control the operation of the local automatic switch train 21, whereby the local automatic switch train 21 operates to seize an idle trunk in the associated group of trunks extending to the repeaters, such as the trunk 37 extending to the repeater 65, the trunk 37 being marked as idle due to the absence of ground potential upon the control conductor C573 thereof. When the local automatic switch train 21 seizes the trunk 37 extending to the repeater 65, operation of the repeater 65 is initiated, in a manner more fully described subsequently.

On the other hand, in the event the call answered at the first operator position 30 is routed thereto by way of the selector repeater 55 and the trunk 35 and is to be extended to the subscriber substation B in the distant exchange 70, the operator at the operator position 30 initiates the extension of the call by operating the key sender 33, thereby to cause a predetermined number of digits corresponding to the switch train routed to the called subscriber substation B in the distant exchange 70 to be registered in the various registers in the key sender 33. The key sender 33 then operates, thereby to cause operation of the selector repeater 55 in a manner similar to that previously explained. More particularly, the first digit registered in the first register 400 in the key sender 33 causes the wiper set of the switching mechanism 300 to be operated in the vertical direction to a corresponding position; whereupon the wiper set of the mechanism 300 is operated automatically in the rotary direction to select an idle trunk in the associated group of trunks extending to the group of repeaters, such as the trunk 37 extending to the repeater 65, in the manner previously explained. The remainder of the digits registered in the various digit registers in the key sender 33 are effective to control the operation of the repeater 65 associated with the trunk 37 by way of the selector repeater 55, in a manner more fully explained subsequently.

In other words, the operator at the first oper-

ator position 30 may cause the trunk 37 extending to the repeater 65 to be seized by way of the local automatic switch train 21 after answering a call originating in the central exchange 20; or she may cause the trunk 37 extending to the repeater 65 to be seized by way of one of the selector repeaters, such as the selector repeater 55, after answering a call originating in the distant exchange 70. The operation of the repeater 65 associated with the trunk 37 is controlled by the various registers in the key sender 33 in an identical manner, regardless of whether the trunk 37 extending to the repeater 65 is seized by way of the local automatic switch train 21 or by way of the selector repeater 55.

More particularly, when the trunk 37 is seized by way of either the local automatic switch train 21 or by way of the selector repeater 55, a path is completed for applying battery potential by way of the register magnet in one of the registers in the key sender 33 to the line conductor C571 of the trunk 37, thereby to complete a circuit for energizing in series the register magnet included in the last-mentioned register in the key sender 33 and the winding of the start relay R525 in the repeater 65. This circuit extends from ground by way of the contacts 531, the winding of R525, the contacts 516, the winding 503 of the repeater transformer 500 and the contacts 561 to the line conductor C571 of the trunk 37 and therefrom by way of either the local automatic switch train 21 or the selector repeater 55 and the operator connecting apparatus 32 at the first operator position 30 to one of the registers in the key sender 33, and therefrom by way of the register magnet in the register to battery. When this series circuit is completed the register magnet in one of the registers in the key sender 33 and the start relay R525 in the repeater 65 operate. Upon operating, the start relay R525 prepares, at the contacts 527, a circuit traced hereinafter for energizing the winding of the dial impulse relay R510 and completes, at the contacts 526, an obvious multiple circuit for energizing the upper winding of the hold relay R550 and the winding of the control relay R520, thereby to cause these relays to operate. Upon operating, the hold relay R550 completes, at the contacts 554, an obvious holding circuit for energizing the winding thereof, including the control conductor C573 of the trunk 37, ground potential being applied to the control conductor C573 of the trunk 37 and either the local automatic switch train 21 or the selector repeater 55. Also, the hold relay R550 completes, at the contacts 551, an obvious alternative point in the previously traced circuit for energizing the winding of the start relay R525 and prepares, at the contacts 555, a point in a holding circuit traced hereinafter for energizing the winding of the pickup relay R540. Also, the hold relay R550 completes, at the contacts 553, an obvious circuit for energizing the lower winding of the answer relay R515. However, when the lower winding of the answer relay R515 is thus energized this relay does not operate, the answer relay R515 being of the polarized type. Finally, the hold relay R550 prepares, at the contacts 552, a circuit traced hereinafter for energizing the upper winding of the answer relay R515.

Upon operating, the control relay R520 completes, at the contacts 521, an obvious path for short-circuiting the winding 503 of the repeater transformer 500, thereby to complete an obvious alternative circuit for energizing the winding of

the start relay R525, excluding the winding 503 of the repeater transformer 500. Also, the control relay R520 completes, at the contacts 522, an obvious path for short-circuiting the winding 502 of the repeater transformer 500 and the condenser 505, thereby to complete a metallic bridge connection between the line conductors C507 and C508 of the trunk line 60 extending to the incoming selector switch 90 in the distant exchange 70. This bridge path extends from the line conductor C507 of the trunk line 60 by way of the contacts 511, the winding 501 of the repeater transformer 500, and the contacts 522 to the line conductor C508 of the trunk line 60. When this metallic bridge path is completed between the line conductors C507 and C508 of the trunk line 60 a loop circuit is completed, including the incoming selector switch 90, thereby to condition the incoming selector switch 90 to be responsive to impulses transmitted thereto over the trunk line 60. Finally, the control relay R520 completes, at the contacts 523, an obvious circuit for energizing the winding of the timing relay R560, thereby to cause the latter relay to operate.

Upon operating, the timing relay R560 interrupts, at the contacts 561, a point in the previously traced original circuit for energizing the winding of the start relay R525, the start relay R525 being retained in its operated position at this time due to the completed alternative circuit for energizing the winding thereof. Also, the timing relay R560 prepares, at the contacts 564, a further point in the previously mentioned holding circuit for energizing the winding of the pickup relay R540 and completes, at the contacts 562, an obvious path for applying ground potential to the start lead C575 extending into the main master impulse generator 22. This application of ground potential to the start lead C575 initiates operation of the main master impulse generator 22 in the event it is not already operating.

The particular mode of operation of the main master impulse generator 22 is explained more fully hereinafter; however, at this time, it is noted that the main master impulse generator 22 operates cyclically in order to cause ground potential to be connected to and then disconnected from the pickup pulse lead C576, the dial pulse lead C577 and the revertive pulse lead C574 extending between the main master impulse generator 22 and the repeater 65, the pickup pulse lead C576, the dial pulse lead C577 and the revertive pulse lead C574 comprising odd pulse leads connected to an odd subgroup of repeaters in the group of repeaters, the odd subgroup of repeaters in the group of repeaters including the repeater 65. Further, it is noted that the main master impulse generator 22 causes ground potential to be connected to the pickup pulse lead C576 momentarily and then causes ground potential to be connected subsequently and substantially simultaneously to the dial pulse lead C577 and the revertive pulse lead C574. Subsequently, ground potential is disconnected from the revertive pulse lead C574; and then, finally, ground potential is disconnected from the dial pulse lead C577. Thereafter, the cycle of connecting ground potential to and disconnecting ground potential from the pickup pulse lead C576, the dial pulse lead C577 and the revertive pulse lead C574 is recompleted repeatedly. The particular mode of operation of the main master impulse generator 22 to connect ground potential

to and to disconnect ground potential from the pulse leads mentioned is explained more fully hereinafter. However, at this point, it is noted that the order of connecting ground potential to and of disconnecting ground potential from the pulse leads mentioned is as follows: Ground potential is first connected to the pickup pulse lead C576; after an interval of time ground potential is disconnected from the pickup pulse lead C576 and is connected to the dial pulse lead C577 and to the revertive pulse lead C574; after an additional interval of time ground potential is disconnected from the revertive pulse lead C574; and after a further interval of time ground potential is reconnected to the pickup pulse lead C576 and ground potential is disconnected from the dial pulse lead C577, thereby to initiate a new cycle of operation. Further, it is noted that the time ratio between the connection of ground potential to and the disconnection of ground potential from the pickup pulse lead C576 is approximately 20:30; the time ratio between the connection of ground potential to and the disconnection of ground potential from the dial pulse lead C577 is approximately 60:40; and the time ratio between the connection of ground potential to and the disconnection of ground potential from the revertive pulse lead C574 is approximately 30:70.

Continuing with the operation of the repeater 65 when ground potential is connected to the pickup pulse lead C576, a circuit is completed for energizing the winding of the pickup relay R540, this circuit extending from the grounded pickup pulse lead C576 by way of the contacts 563 and 545 and the winding of R540 to battery. When thus energized the pickup relay R540 operates to complete, at the contacts 541, an obvious multiple holding circuit for energizing the upper winding of the hold relay R550 and the winding of the control relay R520 and to complete, at the contacts 543, an obvious multiple path for applying ground potential to the start lead C575. Further, the pickup relay R540 completes, at the contacts 544, a holding circuit for energizing the winding thereof, this circuit extending from ground by way of the contacts 564, 555 and 544 and the winding of R540 to battery. Also, the pickup relay R540 interrupts, at the contacts 545, a point in the previously traced original circuit for energizing the winding thereof, prepares, at the contacts 542, an obvious circuit for energizing the upper winding of the revertive impulse relay R530 and prepares, at the contacts 546, a circuit traced hereinafter for energizing the winding of the dial impulse relay R510.

Subsequently, ground potential is connected substantially simultaneously to the dial pulse lead C577 and to the revertive pulse lead C574. When ground potential is connected to the dial pulse lead C577 the previously mentioned circuit for energizing the winding of the dial impulse relay R510 is completed, this circuit extending from the grounded dial pulse lead C577 by way of the contacts 546 and 527 and the winding of R510 to battery. When thus energized the dial impulse relay R510 operates to complete, at the contacts 512, a holding circuit for energizing the winding thereof, this circuit extending from the grounded dial pulse lead C577 by way of the contacts 546 and 512 and the winding of R510 to battery. Also, the dial impulse relay R510 interrupts, at the contacts 513, a point in a circuit traced hereinafter for

energizing the winding of the digit relay R535 and interrupts, at the contacts 511, the previously traced loop circuit extending by way of the trunk line 60 between the repeater transformer 500 in the repeater 65 in the central exchange 20 and the incoming selector switch 90 in the distant exchange 70. When this loop circuit is interrupted the incoming selector switch 90 is operated one step in the vertical direction.

When ground potential is connected to the revertive pulse lead C574 the previously mentioned circuit for energizing the upper winding of the revertive impulse relay R530 is completed, thereby to cause the latter relay to operate. Upon operating, the revertive impulse relay R530 interrupts, at the contacts 531, the previously traced series circuit for energizing the winding of the start relay R525 and the register magnet in one of the registers in the key sender 33 at the operator position 30, thereby to cause the start relay R525 and the register magnet in the one register to restore. Upon restoring, the register magnet in the one register drives the associated ratchet wheel one step in the clockwise direction, in the manner previously explained, thereby to condition the digit switch in the one register to be operated away from its normal position after a predetermined number of restorations of the register magnet corresponding to the digit registered in the one register, in the manner previously explained. Upon restoring, the start relay R525 interrupts, at the contacts 526, the previously mentioned original multiple circuit for energizing the upper winding of the hold relay R550 and the winding of the control relay R520; however, these relays remain in their operated positions at this time due to the completed holding circuit for energizing the upper winding of the hold relay R550 and the winding of the control relay R520. Also, upon restoring, the start relay R525 prepares, at the contacts 528, a circuit traced hereinafter for energizing the winding of the digit relay R535.

Shortly thereafter, ground potential is disconnected from the revertive pulse lead C574 while ground potential is still connected to the dial pulse lead C577. When ground potential is disconnected from the revertive pulse lead C574 at this time, the previously mentioned circuit for energizing the upper winding of the revertive impulse relay R530 is interrupted, thereby to cause the latter relay to restore. Upon restoring, the revertive impulse relay R530 recompletes, at the contacts 531, the previously traced circuit for energizing in series the winding of the start relay R525 and the register magnet in the one register in the key sender 33, thereby to cause the start relay R525 and the register magnet in the one register to reoperate. Upon reoperating, the start relay R525 recompletes, at the contacts 526, the previously mentioned original multiple circuit for energizing the upper winding of the hold relay R550 and the winding of the control relay R520 and interrupts, at the contacts 528, a further point in the previously mentioned circuit for energizing the winding of the digit relay R535.

Subsequently, ground potential is disconnected from the dial pulse lead C577, thereby to interrupt the previously traced circuit for energizing the winding of the dial impulse relay R510 in order to cause the latter relay to restore. Upon restoring, the dial impulse relay R510 interrupts, at the contacts 512, a further point in the previously traced holding circuit for energizing the

winding thereof and prepares, at the contacts 513, a point in the previously mentioned circuit for energizing the winding of the digit relay R535. Also, the dial impulse relay R510 recompiles, at the contacts 511, the previously traced loop circuit extending by way of the trunk line 60 between the repeater transformer 500 and the incoming selector switch 90. When this loop circuit is recompleted the incoming selector switch 90 is conditioned to be operated an additional step in the vertical direction in accordance with the second impulse of the present digit.

Subsequently, ground potential is reconnected substantially simultaneously to the dial pulse lead C577 and to the revertive pulse lead C574, thereby to cause reoperation of the dial impulse relay R510 and reoperation of the revertive impulse relay R530, in the manner previously explained. When the dial impulse relay R510 is reoperated an additional impulse is transmitted over the previously traced loop circuit, including the trunk line 60, to the incoming selector switch 90, thereby to cause the incoming selector switch 90 to be operated an additional step in the vertical direction; and when the revertive impulse relay R530 is reoperated the start relay R525 in the repeater 65 and the register magnet in the one register in the key sender 33 restore, in the manner previously explained, a new cycle of operation of the main master impulse generator 22 being initiated at this time.

Accordingly, the dial impulse relay R510, the revertive impulse relay R530 and the start relay R525 in the repeater 65 interact in the manner described above repeatedly, thereby to cause a number of impulses to be transmitted by way of the trunk line 60 to the incoming selector switch 90 and to cause the register magnet in the one register in the key sender 33 to be repeatedly restored, in the manner previously explained. Hence, at this time, a number of impulses corresponding to the digit registered in the one register in the key sender 33 is transmitted by way of the trunk line 60 to the incoming selector switch 90 and the register magnet in the one register is restored a corresponding number of times, thereby to cause the register switch in the one register to be operated away from its normal position. Thus it will be understood that, when a number of impulses corresponding to the digit registered in the one register in the key sender 33 is transmitted to the incoming selector switch 90, the register switch in the one register is operated away from its normal position, thereby to transfer the control circuit for energizing the winding of the start relay R525 in the repeater 65 from the one register in the key sender 33 to another register in the key sender 33; after which the repeater 65 is controlled in accordance with the digit registered in the other register in the key sender 33, in the manner described above, in connection with the control of the repeater 65 in accordance with the digit registered in the one register in the key sender 33.

At this point it is noted that, when the register switch in the one register in the key sender 33 is operated to disassociate the control circuit for energizing the winding of the start relay R525 from the register magnet in the one register to the register magnet in the other register in the key sender 33, there is a time delay in the other register before battery potential is applied by way of the register magnet in the

other register to the line conductor C571 of the trunk 37, the line conductor C571 of the trunk 37 being included in the previously traced circuit for energizing the winding of the start relay R525 in the repeater 65. Accordingly, the start relay R525 in the repeater 65 remains in its restored position for a predetermined time interval subsequent to the transfer of the control circuit for energizing the winding thereof from the one register to the other register in the key sender 33.

Continuing now with the operation of the repeater 65, the main master impulse generator 22 reoperates, thereby to connect ground potential substantially simultaneously to the dial pulse lead C577 and to the revertive pulse lead C574, while the start relay R525 occupies its restored position. At this time, when ground potential is connected to the dial pulse lead C577, the previously mentioned circuit for energizing the winding of the digit relay R535 is completed, this circuit extending from the grounded dial pulse lead C577 by way of the contacts 546, 528 and 513 and the winding of R535 to battery. When thus energized the digit relay R535 operates to complete, at the contacts 537, an obvious holding circuit for energizing the lower winding of the revertive impulse relay R530, the upper winding of the revertive impulse relay R530 being energized incident to the connection of ground potential to the revertive pulse lead C574, as previously explained. Further, the digit relay R535 interrupts, at the contacts 536, the previously mentioned multiple holding circuit for energizing the upper winding of the hold relay R550 and the winding of the control relay R520. Subsequently, ground potential is disconnected from the revertive pulse lead C574, thereby to interrupt the previously mentioned circuit for energizing the upper winding of the revertive impulse relay R530, in the manner previously explained; however, the revertive impulse relay R530 does not restore at this time due to the completed holding circuit for energizing the lower winding thereof. Accordingly, the operated revertive impulse relay R530 retains interrupted, at the contacts 531, the previously traced circuit for energizing the winding of the start relay R525. Hence, it will be understood that the previously traced circuit for energizing the winding of the start relay R525 is not immediately recompleted at this time when the other register in the key sender 33 operates to cause battery potential to be applied by way of the winding of the register magnet therein to the line conductor C571 of the trunk 37, in the manner previously explained. Hence, the start relay R525 is retained in its restored position for a predetermined time interval at this time.

When the previously mentioned multiple holding circuit for energizing the upper winding of the hold relay R550 and the winding of the control relay R520 is interrupted the control relay R520 restores; however, the hold relay R550 remains in its operated position due to the completed holding circuit for energizing the lower winding thereof. Upon restoring, the control relay R520 interrupts, at the contacts 523, the previously mentioned circuit for energizing the winding of the timing relay R560, thereby to cause the latter relay to restore shortly thereafter, the timing relay R560 being of the slow-to-release type. Also, upon restoring, the control relay R520 interrupts, at the contacts 522, the previously traced metallic bridge circuit, includ-

ing the winding 501 of the repeater transformer 500 between the line conductors C507 and C508 of the trunk line 60; whereupon, the previously traced resistance bridge connection including the windings 501 and 502 of the repeater transformer 500, the resistor 514 and the upper winding of the answer relay R515 is completed between the line conductors C507 and C508 of the trunk line 60. When the direct metallic bridge circuit between the line conductors C507 and C508 of the trunk line 60 is interrupted and the resistance bridge connection between the line conductors C507 and C508 of the trunk line 60 is recompleted, the incoming selector switch 90 in the distant exchange 70 is controlled, thereby to cause the incoming selector switch 90 to operate automatically in the rotary direction and search for an idle trunk in the group of trunks previously selected due to the operation thereof in the vertical direction, in a well-known manner. For purpose of illustration, it is assumed that the incoming selector switch 90 seizes the trunk 96 extending to the connector switch 95; whereupon the connector switch 95 is rendered responsive to two digits transmitted thereto, in a well-known manner.

Continuing with the operation of the repeater 65 after a brief time interval, the timing relay R560 restores, as previously noted, in order to interrupt, at the contacts 562, the previously mentioned original path for applying ground potential to the start lead C575; to interrupt, at the contacts 563, the previously traced original circuit for energizing the winding of the pickup relay R540; and to interrupt, at the contacts 564, the previously traced holding circuit for energizing the winding of the pickup relay R540, thereby to cause the latter relay to restore. Upon restoring, the pickup relay R540 interrupts, at the contacts 543, the previously mentioned alternative path for applying ground potential to the start lead C575; however, operation of the main master pulse generator 22 is not arrested necessarily as other of the repeaters may be operating at this time. Also, the pickup relay R540 interrupts, at the contacts 541, a further point in the previously mentioned multiple circuit for energizing the upper winding of the hold relay R550 and the winding of the control relay R520, and interrupts, at the contacts 542, the previously mentioned circuit for energizing the upper winding of the revertive impulse relay R530 in the event ground potential is connected to the revertive pulse lead C574 at this time. Further, the pickup relay R540 interrupts, at the contacts 544, a further point in the previously traced holding circuit for energizing the winding thereof and prepares, at the contacts 545, a point in the previously traced original circuit for energizing the winding of the pickup relay R540. Finally, the pickup relay R540 interrupts, at the contacts 546, the previously traced circuit for energizing the winding of the digit relay R535, thereby to cause the latter relay to restore shortly thereafter, the digit relay R535 being of the slow-to-release type. At this point it is noted that the digit relay R535, being of the slow-to-release type, does not restore during the interval of time while ground potential is disconnected from the dial pulse lead C577 prior to the restoration of the pickup relay R540. Upon restoring, the digit relay R535 prepares, at the contacts 536, a further point in the previously traced original multiple circuit for energizing the upper winding of the hold relay R550 and the winding of the con-

trol relay R520, and interrupts, at the contacts 537, the previously mentioned holding circuit for energizing the lower winding of the revertive impulse relay R530, thereby to cause the latter relay to restore.

Upon restoring, the revertive impulse relay R530 recomplete, at the contacts 531, a circuit substantially identical to that previously traced for energizing in series the winding of the start relay R525 in the repeater 65 and the register magnet in the other register in the key sender 33, whereupon the start relay R525 and the register magnet in the other register operate. Upon operating, the start relay R525 initiates reoperation of the repeater 65 in accordance with the digit registered in the other register in the key sender 33, in the manner previously explained. At this point, it is noted that, prior to reoperation of the start relay R525 and the consequent initiation of another cycle of operation of the repeater 65, the incoming selector switch 90 has adequate time to select the trunk 96 extending to the connector switch 95 due to the slow-to-release characteristics of the timing relay R560 and the digit relay R535. The subsequent operation of the repeater 65 incident to the reoperation of the start relay R525 is the same as that previously explained; accordingly, the repeater 65 is operated in order to cause the impulses corresponding to the digit registered in the other register in the key sender 33 to be transmitted over the trunk line 60, the incoming selector switch 90 and the trunk 96 to the connector switch 95. Thereafter, the repeater 65 operates through a further cycle, thereby to cause a further digit to be transmitted to the connector switch 95 corresponding to a digit registered in a further register in the key sender 33. Following the transmission of the further or second digit to the connector switch 95 in the distant exchange 70, the register magnet in the further register in the key sender 33 operates to cause battery potential to be removed from the line conductor C571 of the trunk 37 and no further application of battery potential to the line conductor C571 of the trunk 37 is made in the key sender 33 as the key sender 33 is completely cleared at this time.

When the registers in the key sender 33 are completely cleared at this time, ground potential is removed from the trunk conductor C432, thereby to cause the local automatic switch train 21 to be completely operated, in the event the call extended to the distant exchange 70 originated in the central exchange 20, or to cause the send relay R345 and the answer relay R350 in the selector repeater 55 to restore, whereupon the selector repeater 55 is completely operated, in the event the call extended to the distant exchange 70 originated in the distant exchange. Also, when the local automatic switch train 21 or the selector repeater 55 is completely operated a signal is transmitted to the first operator position 30, thereby to cause one of the answer lamps in the operator connecting apparatus 32 to be illuminated more brightly, as previously explained. More particularly, the answer lamp L446 individually associated with the connect key K440 in the operator connecting apparatus 32 is thus illuminated in the event the call is routed over the repeater 65 by way of the selector repeater 55; on the other hand, an answer lamp, not shown, individually associated with the connect key K445 in the operator connecting apparatus 32 is thus illuminated in the event the call

is routed over the repeater 65 by way of the local automatic switch train 21. The operator at the first operator position 30 then operates the proper connect key K440 or K445 to its normal position, thereby completely to release the apparatus at the operator position 30.

Continuing now with the operation of the repeater 65 subsequent to the transmission of all of the digits over the trunk line 60 to the distant exchange 70, all of the relays in the repeater 65, with the exception of the hold relay R550, are restored, in the manner previously explained, and operation of the main master impulse generator 22 is arrested in the event none of the other repeaters is operated at this time. In response to the two digits transmitted to the connector switch 95 in the distant exchange 70, the connector switch 95 operates, thereby to select the telephone line 72 extending to the subscribed substation B in the distant exchange 70. The subsequent operation of the connector switch 95 depends upon the idle or busy condition of the subscriber substation B.

In the event the subscriber substation B is busy at this time, busy tone current is returned from the connector switch 95 over the previously traced loop circuit, including the trunk 96, the incoming selector switch 90 and the trunk line 60 to the repeater transformer 500. On the other hand, in the event the subscriber substation B is idle at this time, ringing current is projected from the connector switch 95 over the telephone line 72 extending thereto and ring-back tone current is returned from the connector switch 95 over the previously traced loop circuit, including the trunk 96, the incoming selector switch 90 and the trunk line 60 to the repeater transformer 500. The busy tone current returned to the repeater transformer 500 or the ring-back tone current returned thereto is repeated by the repeater transformer 500 over the trunk 37. In the event the call originated at the calling subscriber substation C in the central exchange 20, this tone current is conducted from the trunk 37 by way of the local automatic switch train 21 and the telephone line 41 to the calling subscriber substation C; on the other hand, in the event the call originated at the calling subscriber substation A in the distant exchange 70, this tone current is conducted from the trunk 37 by way of the selector repeater 55, the trunk line 50, the trunk circuit 80, the trunk 81, the non-numerical automatic switch 78 and the telephone line 71 to the calling subscriber substation A.

Assuming that the called subscriber substation B in the distant exchange 70 is idle at this time, when the subscriber thereat answers the call by removing the receiver of the telephone instrument at the subscriber substation B from its associated switchhook a loop circuit is completed between the called subscriber substation B and the connector switch 95, including the telephone line 72; whereupon the connector switch 95 operates to cause battery to be reversed over the previously traced loop circuit extending between the connector switch 95 and the repeater transformer 500 in the repeater 65, this loop circuit including the upper winding of the answer relay R515 in the repeater 65, as previously noted. When the upper winding of the answer relay R515 is thus energized, the lower winding thereof being energized at this time, the answer relay R515 operates, this relay being of the polarized type, as previously noted.

Upon operating, the answer relay R515 interrupts, at the contacts 516, a further point in the previously traced circuit for energizing the winding of the start relay R525 and completes, at the contacts 517, a metallic circuit between the line conductors C571 and C572 of the trunk 37, this connection extending from the line conductor C571 of the trunk 37 by way of the contacts 551, the winding 503 of the repeater transformer 500, the contacts 517, the resistor 509 and the winding 504 of the repeater transformer 500 to the line conductor C572 of the trunk 37. The completion of the metallic circuit between the line conductors C571 and C572 of the trunk 37 may be utilized for supervisory purposes in the local automatic switch train 21; however, it is not utilized in the selector repeater 55. Also when the connector switch 95 seizes the telephone line 72 extending to the called subscriber substation B in the distant exchange 70, the line circuit 76 individually associated with the telephone line 72 operates, thereby to mark the telephone line 72 as busy to the connector switches having access thereto.

Accordingly, at this time, an established connection is completed from the calling subscriber substation C in the central exchange 20 by way of the telephone line 41 and the local automatic switch train 21 to the trunk 37 or from the calling subscriber substation A in the distant exchange 70 by way of the telephone line 71, the non-numerical automatic switch 78, the trunk 81, the trunk circuit 80, the trunk line 50, and the selector repeater 55 to the trunk 37; further, the connection is completed from the trunk 37 by way of the repeater 65, the trunk line 60, the incoming selector switch 90, the trunk 96, the connector switch 95 and the telephone line 72 to the called subscriber substation B in the distant exchange 70.

The release of this established connection is under the control of the subscriber at the calling subscriber substation A, in the event the connection is completed between the calling subscriber substation A in the distant exchange 70 and the called subscriber substation B in the distant exchange 70. The release of the established connection is effected when the subscriber at the calling subscriber substation A replaces the receiver of the telephone instrument thereat upon its associated switchhook. When the subscriber at the calling subscriber substation A replaces the receiver of the telephone instrument thereat upon its associated switchhook the line circuit 75 individually associated with the telephone line 71 extending to the subscriber substation A is controlled, thereby to effect the release of the non-numerical automatic switch 78, the trunk circuit 80 and the selector repeater 55, in the manner previously explained. When the selector repeater 55 is released the trunk 37 is released, thereby to interrupt the previously traced circuit for applying ground potential to the control conductor C513 thereof. On the other hand, in the event the connection is completed between the calling subscriber substation C in the central exchange 20 and the called subscriber substation B in the distant exchange 70, the release of the established connection is effected when the subscriber at the calling subscriber substation C replaces the receiver of the telephone instrument thereat upon its associated switchhook. When the subscriber at the calling subscriber substation C replaces the receiver of the telephone instrument thereat upon its asso-

ciated switchhook, the line circuit 45 individually associated with the telephone line 41 extending to the subscriber substation C is controlled, thereby to effect the release of the local automatic switch train 21 and to mark the telephone line 41 as idle to the switches having access thereto. When the local automatic switch train 21 is released the trunk 37 is released, thereby to cause ground potential to be removed from the control conductor C573 thereof.

When ground potential is removed from the control conductor C573 of the trunk 37, the previously mentioned holding circuit for energizing the lower winding of the hold relay R550 in the repeater 65 is interrupted, thereby to cause the latter relay to restore. Upon restoring, the hold relay R550 interrupts, at the contacts 553, the previously traced circuit for energizing the lower winding of the answer relay R515 and interrupts, at the contacts 552, the previously traced loop circuit extending between the repeater transformer 500 and the connector switch 95 in the distant exchange 70 including the upper winding of the answer relay R515, thereby to cause the answer relay R515 to restore. At this time, the repeater 65 is completely released and ground potential is removed from the control conductor C573 of the trunk 37 extending thereto, thereby to mark the trunk 37 as idle to the switches having access thereto. When the loop circuit between the repeater transformer 500 in the repeater 65 in the central exchange 20 and the connector switch 95 in the distant exchange 70 is interrupted, both the connector switch 95 and the incoming selector switch 90 in the distant exchange 70 are released. When the connector switch 95 is released the line circuit 76 individually associated with the telephone line 72 extending to the called subscriber substation B in the distant exchange 70 is controlled, thereby to mark the telephone line 72 as idle to the connector switches having access thereto in the event the subscriber at the called subscriber substation B has replaced the receiver of the telephone instrument thereat upon its associated switchhook at this time, or to lock the telephone line 72 out of service in the event the subscriber at the subscriber substation B has not replaced the receiver of the telephone instrument thereat upon its associated switchhook at this time.

In view of the foregoing explanation of the mode of operation of the apparatus incorporated in the central exchange 20 and the distant exchange 70, it will be understood that all calls between the subscriber substations in the distant exchange 70 and all calls in either direction between the subscriber substations in the central exchange 20 and the distant exchange 70 are completed with the assistance of the operators at the operator positions in the central exchange 20. Also, all calls between the subscriber substations in the central exchange 20 are completed with the assistance of the operators at the operator positions in the central exchange 20.

For example, a call between the subscriber substation C and the subscriber substation D in the central exchange 20 is first initiated at the calling subscriber substation C, thereby to cause the line circuit 45 individually associated with the telephone line 41 extending to the calling subscriber substation C to operate. Upon operating, the line circuit 45 causes the local automatic switch train 21 to seize the telephone line 41 and to seize a trunk extending to the operator

positions, such as the trunk 34. When the telephone line 41 is seized by the local automatic switch train 21 the line circuit 45 is operated, thereby to mark the telephone line 41 as busy to the switches in the local automatic switch train 21 having access thereto. The operator at the first operator position 30 may answer the call on the trunk 34 by operating the connect key K445 in the operator connecting apparatus 32, in the manner previously explained. The operator at the first operator position 30 is then advised concerning the extension of the call to the called subscriber substation D and then operates the key sender 33, thereby to control the operation of the local automatic switch train 21, whereupon the local automatic switch train 21 operates to seize the telephone line 42 extending to the called subscriber substation D. The subsequent operation of the local automatic switch train 21 depends upon the idle or busy condition of the called subscriber substation D in accordance with conventional practice. After the local automatic switch train 21 seizes the telephone line 42 extending to the called subscriber substation D, a signal is transmitted therefrom by way of the trunk 34 to the first operator position 30 in order to indicate to the operator thereat that the local automatic switch train 21 has operated to seize the telephone line 42 extending to the called subscriber substation D. The operator at the first operator position 30 then returns the connect key K445 in the operator connecting apparatus 32 to its normal position, thereby to release the apparatus at the first operator position 30. More particularly, the local automatic switch train 21 operates to cause busy tone current to be returned over the telephone line 41 to the calling subscriber substation C in the event the called subscriber substation D is busy at this time. On the other hand, in the event the called subscriber substation D is idle at this time, the local automatic switch train 21 operates to cause ringing current to be projected over the telephone line 42 to the called subscriber substation D and ring-back tone current to be returned over the telephone line 41 to the calling subscriber substation C. Assuming that the called subscriber substation D is idle at this time, when the subscriber thereat answers the call by removing the receiver of the telephone instrument at the substation D from its associated switchhook the line circuit 46 operates, thereby to mark the telephone line 42 as busy to the switches in the local automatic switch train 21 having access thereto and to cause the local automatic switch train 21 to complete an established connection between the calling subscriber substation C and the called subscriber substation D. The release of this established connection is under the control of the subscriber at the calling subscriber substation C and is effective when the subscriber thereat replaces the receiver of the telephone instrument at the subscriber substation C upon its associated switchhook, thereby to cause operation of the line circuit 45. The line circuit 45 then operates, thereby to cause the local automatic switch train 21 to be released and to mark the telephone line 41 as idle to the switches having access thereto. When the local automatic switch train 21 is released the line circuit 46 operates to mark the telephone line 42 as idle in the event the subscriber at the called subscriber substation D has replaced the receiver of the telephone instrument thereat upon its asso-

ciated switch-hook at this time; and operates to lock the telephone line 42 out of service in the event the subscriber at the called subscriber substation D has not replaced the receiver of the telephone instrument thereat upon its associated switch-hook at this time.

Considering now the connection and arrangement and mode of operation of the main master impulse generator 22, it is noted that the main master impulse generator 22 comprises an odd set of pulse leads, including the pickup pulse lead C576, the dial pulse lead C517 and the revertive pulse lead C574; and an even set of pulse leads, including the pickup pulse lead C685, the dial pulse lead C687 and the revertive pulse lead C686. The odd set of pulse leads is commonly connected to the repeaters in the odd sub-groups of repeaters in the associated group; while the even set of pulse leads is commonly connected to the repeaters in the even subgroup of repeaters in the associated group. Accordingly, the main master impulse generator 22 is operative to control in multiple a number of repeaters in both the odd and even subgroups of repeaters in the associated group, as will appear more fully hereinafter.

When ground potential is applied to the start lead C575 in any one of the repeaters in the associated group, an obvious circuit is completed for energizing the winding of the lockout relay R660, thereby to cause the latter relay to operate shortly thereafter, the lockout relay R660 being of the slow-to-operate type. Also when ground potential is applied to the start lead C575 a path is completed for applying ground potential to the terminals of the resistors 606 and 607, this path extending from the grounded start lead C575 by way of the contacts 674 and 664 and the choke coil 608 to the terminals of the resistors 606 and 607. Accordingly, ground potential is applied to the terminals of the resistors 606 and 607 prior to operation of the lockout relay R660, the latter relay being of the slow-to-operate type. The application of ground potential to the terminals of the resistors 606 and 607 completes a circuit for energizing either the upper winding or the lower winding of the start relay R640, depending upon the restored or operated position of the cycle relay R620. More particularly, when the cycle relay R620 occupies its restored position the application of ground potential to the terminal of the resistor 607 completes an obvious circuit for energizing the lower winding of the start relay R640, the resistor 607 being short-circuited at this time due to the closed contact 622' and the resistor 606 being encircuited due to the open contact 621', the contacts 622' and 621' being controlled by the cycle relay R620, in a manner more fully explained hereinafter. When the lower winding of the start relay R640 is thus energized this relay operates to complete, at the contacts 643, an alternative path for applying ground potential to the terminals of the resistors 606 and 607, this path extending from the grounded start lead C575 by way of the contacts 674 and 643, and the choke coil 608 to the terminals of the resistors 606 and 607. Also the start relay 640 completes, at the contacts 641, an obvious circuit for illuminating the signal lamp L617, thereby to indicate to the exchange attendant that the main master impulse generator 22 is operating. Further the start relay R640 prepares, at the contacts 642, circuits traced hereinafter for energizing the upper and intermediate windings of the cycle relay R630, in a manner more fully explained subsequently.

At this point it is noted that the condensers 644 and 645 are normally charged in series parallel relationship, the circuit for charging the condenser 644 extending from ground by way of the winding of the timing relay R650, the condenser 644 and the upper winding of the start relay R640 to battery, and the circuit for charging the condenser 645 extending from ground by way of the winding of the timing relay R650, the condenser 645 and the lower winding of the start relay R640 to battery. Accordingly, at this time, when the cycle relay R620 occupies its restored position the application of ground potential to the terminals of the resistors 606 and 607 not only completes an obvious circuit for energizing the lower winding of the start relay R640, but also an obvious path for discharging the condenser 645, and does not substantially affect the path for charging the condenser 644. Accordingly, at this time, the condenser 645 is discharged while the condenser 644 remains charged. More particularly, the condenser 645 is discharged through the winding of the timing relay R650, thereby to cause the latter relay to operate. After the condenser 645 is discharged through the winding of the timing relay R650 the latter relay restores. On the other hand, when the cycle relay R620 occupies its operated position the application of ground potential to the terminals of the resistors 606 and 607 completes an obvious circuit for energizing the upper winding of the start relay R640 and an obvious path for discharging the condenser 644, and causes the condenser 645 to be recharged. Accordingly, at this time, the condenser 644 is discharged while the condenser 645 is charged. More particularly, the condenser 644 is discharged through the winding of the timing relay R650, thereby to cause the latter relay to operate. After the condenser 644 is discharged through the winding of the timing relay R650 the latter relay restores. Accordingly, the operation and subsequent restoration of the cycle relay R620 causes the condenser 644 to be discharged and the condenser 645 to be charged and then causes the condenser 645 to be discharged and the condenser 644 to be charged. Hence, as the cycle relay R620 operates and restores, the condensers 644 and 645 are charged and discharged through the winding of the timing relay R650, thereby to cause the timing relay R650 to operate and restore intermittently. In the event the main master impulse generator 22 is operating properly the cycle relay R620 is operating and restoring upon a predetermined cycle, thereby to cause operation and restoration of the timing relay R650 on a predetermined cycle.

It is noted that prior to the operation of the lockout relay R660 a circuit is normally completed for energizing in series the upper and lower windings of the hold relay R670, this circuit extending from ground by way of the contacts 672 and 663 and the lower and upper windings of R670 to battery. The operated hold relay R670 retains completed, at the contacts 672, the previously traced holding circuit for energizing in series the lower and upper windings thereof, retains prepared, at the contacts 671, circuits traced hereinafter for energizing the windings of the pulse relays R600 and R610 and the windings of the cycle relays R620 and R630, in a manner more fully explained hereinafter, and retains prepared, at the contacts 674, the previously traced circuit for energizing the winding

of the lockout relay R660. Accordingly, when the lockout relay R660 operates, it interrupts, at the contacts 664, the previously traced original path for applying ground potential to the terminals of the resistors 606 and 607, ground potential being applied to the terminals of the resistors 606 and 607 at this time due to the completed alternative path for applying ground potential thereto, the start relay R640 occupying its operated position at this time. Also upon operating, the lockout relay R660 interrupts, at the contacts 663, the previously traced original holding circuit for energizing in series the upper and lower windings of the hold relay R670, whereby an alternative resistance holding circuit is completed for energizing in series the upper and lower windings of the hold relay R670, this resistance holding circuit extending from ground by way of the contacts 672, the resistor 652 and the lower and upper windings R670 to battery. At this point it is noted that the upper and lower windings of the hold relay R670 are not sufficiently energized by way of the above-traced resistance holding circuit due to the high series resistance thereof in order to retain the hold relay R670 in its operated position. Accordingly, the hold relay R670 tends to restore shortly after the lockout relay R660 operates to interrupt, at the contacts 663, the previously traced original holding circuit for energizing in series the upper and lower windings of the hold relay R670, the hold relay R670 being of the slow-to-release type. However, each time the timing relay R650 operates it completes, at the contacts 651, an obvious holding circuit for energizing the upper winding of the hold relay R670, thereby to retain the hold relay R670 in its operated position. Accordingly, it will be understood that the hold relay R670 tends to restore while the lockout relay R660 is operated; while the operation of the timing relay R650 prevents restoration of the hold relay R670. Thus it will be understood that the hold relay R670 is retained in its operated position only in the event the timing relay R650 operates intermittently upon the previously mentioned predetermined cycle and at a predetermined rate within given limits.

Accordingly, in the event the cycle relay R620 fails to operate and restore upon its proper cycle at a predetermined rate within given limits, the timing relay R650 fails to operate and restore upon its proper cycle; in this event the holding circuit for energizing the upper winding of the hold relay R670 is not recompleted upon the proper cycle, whereupon the hold relay R670 restores. Upon restoring, the hold relay R670 interrupts, at the contacts 672, the previously traced resistance holding circuit for energizing in series the upper and lower windings thereof and a further point in the previously traced holding circuit for energizing the upper winding thereof, and interrupts, at the contacts 674, the previously mentioned circuit for energizing the winding of the lockout relay R660 and the previously traced path for applying ground potential to the terminals of the resistors 606 and 607, whereupon the previously traced circuits for energizing the upper and lower windings of the start relay R640 are interrupted. Accordingly, in this event, both the lockout relay R660 and the start relay R640 restore. Further the hold relay R670 completes, at the contacts 673, an obvious circuit for illuminating the signal lamp L618, thereby to indicate to the exchange attendant that the main master impulse generator 22 has

failed to operate properly. Finally, the hold relay R670 completes, at the contacts 675, an obvious connection between the start conductor C575 and the control conductor C684 extending to the auxiliary master impulse generator 23. The application of ground potential to the control conductor C684 extending to the auxiliary master impulse generator 23 initiates operation thereof, whereby the repeaters are controlled by the auxiliary master impulse generator 23 instead of by the main master impulse generator 22.

After the main master impulse generator 22 has been repaired such that the cycle relay R620 operates and restores upon its predetermined cycle, reoperation of the main master impulse generator 22 may be initiated by momentarily operating the reset key K676, thereby to complete an obvious starting circuit for energizing in series the upper and lower windings of the hold relay R670. When thus energized the hold relay R670 operates to recomplete, at the contacts 672, the previously traced holding circuit for energizing in series the upper and lower windings of the hold relay R670. Further the hold relay R670 interrupts, at the contacts 675, the previously traced connection between the start conductor C575 and the control conductor C684 extending to the auxiliary master impulse generator 23, whereupon operation of the auxiliary master impulse generator 23 is arrested. Accordingly, at this time, the repeaters are again controlled by the main master impulse generator 22 instead of by the auxiliary master impulse generator 23.

Considering now more particularly the mode of operation of the main master impulse generator 22, it is noted that the interrupter I680 operates continuously to transmit twenty ground impulses per second to each of the control conductors C681 and C682, ground potential being applied to the control conductors C681 and C682 alternately. Accordingly, when the lockout relay R660 operates, the start relay R640 having previously operated, it prepares, at the contacts 662, a circuit traced hereinafter for energizing the upper winding of the cycle relay R630. When the interrupter I680 operates to apply the first ground pulse to the control conductor C682 the previously mentioned circuit for energizing the upper winding of the cycle relay R630 is completed, this circuit extending from ground by way of the conductor C683, the interrupter I680, C682, the contacts 662, 642 and 627 and the upper winding of R630 to battery. When the upper winding of the cycle relay R630 is thus energized this relay operates to complete, at the contacts 635, a holding circuit for energizing the lower winding thereof, this circuit extending from ground by way of the contacts 641 and 635 and the lower winding of R630 to battery. Also the cycle relay R630 prepares, at the contacts 636, a circuit traced hereinafter for energizing the intermediate winding thereof and prepares, at the contacts 634, a circuit traced hereinafter for energizing the upper winding of the cycle relay R620. When the interrupter I680 operates to apply the first ground pulse to the control conductor C681 the previously mentioned circuit for energizing the upper winding of the cycle relay R620 is completed, this circuit extending from ground by way of the conductor C683, the interrupter I680, C681, the contacts 634 and the upper winding of R620 to battery. When the upper winding of the cycle relay R620 is thus en-

ergized this relay operates to complete, at the contacts 625, a holding circuit for energizing the lower winding thereof, this circuit extending from ground by way of the contacts 641 and 625, and the lower winding of R620 to battery. Also the cycle relay R620 prepares, at the contacts 624, a point in a circuit traced hereinafter for energizing the intermediate winding thereof and prepares, at the contacts 626, a further point in the previously mentioned circuit for energizing the intermediate winding of the cycle relay R630.

When the interrupter I680 operates to apply the second ground pulse to the control conductor C682, the previously mentioned circuit for energizing the intermediate winding of the cycle relay R630 is completed, this circuit extending from ground by way of the conductor C683, the interrupter I680, C682, the contacts 662, 642, 626 and 636 and the intermediate winding of R630 to battery. When the intermediate winding of the cycle relay R630 is thus energized this relay restores, the lower winding thereof being energized at this time, as the cycle relay R630 is of the differential type, the intermediate and lower windings thereof opposing each other. Upon restoring, the cycle relay R630 interrupts, at the contacts 636, the previously traced circuit for energizing the intermediate winding thereof and interrupts, at the contacts 635, the previously traced holding circuit for energizing the lower winding thereof, the resistor 647 being encircuited in the series circuit for energizing the lower winding of the cycle relay R630. Further the cycle relay R630 interrupts, at the contacts 634, a further point in the previously traced circuit for energizing the upper winding of the cycle relay R620 and prepares, at the contacts 633, a further point in the previously mentioned circuit for energizing the intermediate winding of the cycle relay R620. When the interrupter I680 operates to apply the second ground pulse to the control conductor C681, the previously mentioned circuit for energizing the intermediate winding of the cycle relay R620 is completed, this circuit extending from ground by way of the conductor C683, the interrupter I680, C681, the contacts 633 and 624 and the intermediate winding of R620 to battery. When the intermediate winding of the cycle relay R620 is thus energized this relay restores, the lower winding thereof being energized at this time, as the cycle relay R620 is of the differential type, the intermediate and lower windings thereof opposing each other. Upon restoring, the cycle relay R620 interrupts, at the contacts 624, the previously traced circuit for energizing the intermediate winding thereof and interrupts, at the contacts 625, the previously traced holding circuit for energizing the lower winding thereof, the resistor 646 being encircuited in the series circuit for energizing the lower winding of the cycle relay R620. Further the cycle relay R620 interrupts, at the contacts 626, a further point in the previously traced circuit for energizing the intermediate winding of the cycle relay R630 and prepares, at the contacts 621, a further point in the previously traced circuit for energizing the upper winding of the cycle relay R630.

In view of the foregoing explanation of the mode of operation and restoration of the cycle relays R620 and R630, it will be understood that the cycle relays R630 and R620 operate successively in the order named; and that subsequently the cycle relays R630 and R620 then restore suc-

cessively in the order named, thereby to complete one cycle of operation of the main master impulse generator 22, this cyclic operation of the cycle relays R620 and R630 continuing repeatedly while the main master impulse generator 22 is in operation.

Considering now the operation of the pulse relays R600 and R610, it is noted that, when the cycle relay R630 operates, while the cycle relay R620 occupies its restored position, it interrupts, at the contacts 631, a circuit traced hereinafter for energizing the winding of the pulse relay R610 and completes, at the contacts 632, a circuit for energizing the winding of the pulse relay R600. The last-mentioned circuit extends from ground by way of the contacts 671 and 661, the choke coil 616, the contacts 632 and the winding of R600 to battery. When thus energized the pulse relay R600 operates to prepare, at the contacts 602, a holding circuit for energizing the winding thereof and to prepare, at the contacts 601, a holding circuit traced hereinafter for energizing the winding of the pulse relay R610. When the cycle relay R620 operates, while the cycle relay R630 occupies its operated position, it prepares, at the contacts 621, a point in a circuit traced hereinafter for energizing the winding of the pulse relay R610, interrupts, at the contacts 622, a point in the previously mentioned holding circuit for energizing the winding of the pulse relay R610 and completes, at the contacts 623, the previously mentioned holding circuit for energizing the winding of the pulse relay R600. The last-mentioned circuit extends from ground by way of the contacts 671 and 661, the choke coil 616, the resistor 615, the contacts 623 and 602 and the winding of R600 to battery. When the cycle relay R630 restores, while the cycle relay R620 occupies its operated position, it interrupts, at the contacts 632, the previously traced original circuit for energizing the winding of the pulse relay R600, the pulse relay R600 being retained in its operated position at this time due to the completed holding circuit for energizing the winding thereof. Also the cycle relay R630 completes, at the contacts 631, the previously mentioned circuit for energizing the winding of the pulse relay R610, this circuit extending from ground by way of the contacts 671 and 661, the choke coil 616, the contacts 631 and 621 and the winding of R610 to battery. When thus energized the pulse relay R610 operates to complete, at the contacts 611, the previously mentioned holding circuit for energizing the winding thereof, this circuit extending from ground by way of the contacts 671 and 661, the choke coil 616, the contacts 631 and the contacts 601 and 611 in multiple and the winding of R610 to battery. When the cycle relay R620 restores, while the cycle relay R630 occupies its restored position, it interrupts, at the contacts 621, the previously traced original circuit for energizing the winding of the pulse relay R610 and completes, at the contacts 622, a further multiple holding circuit for energizing the winding of the pulse relay R610, this circuit extending from ground by way of the contacts 671 and 661, the choke coil 616, the resistor 615, the contacts 622 and 611 and the winding of R610 to battery. Further the cycle relay R620 interrupts, at the contacts 623, the previously traced holding circuit for energizing the winding of the pulse relay R600, thereby to cause the latter relay to restore. Upon restoring, the pulse relay R600 interrupts, at the contacts 601, a point in the multiple holding circuit

for energizing the winding of the pulse relay R610 and interrupts, at the contacts 602, a further point in the previously traced holding circuit for energizing the winding thereof.

Considering now another cycle of operation of the cycle relays R620 and R630, when the cycle relay R630 reoperates while the cycle relay R620 occupies its restored position, it interrupts, at the contacts 631, the previously traced original circuit for energizing the winding of the pulse relay R610, the pulse relay R610 being retained in its operated position due to the completed holding circuit for energizing the winding thereof. Also the cycle relay R630 completes, at the contacts 632, the previously traced circuit for energizing the winding of the pulse relay R600, thereby to cause the latter relay to reoperate. Upon reoperating, the pulse relay R600 re-prepares, at the contacts 602, the previously traced holding circuit for energizing the winding thereof and re-prepares, at the contacts 601, a point in the previously traced holding circuit for energizing the winding of the pulse relay R610. When the cycle relay R620 operates, while the cycle relay R630 occupies its operated position, it reprepares, at the contacts 621, the previously traced original circuit for energizing the winding of the pulse relay R610, and interrupts, at the contacts 622, the previously traced holding circuit for energizing the winding of the pulse relay R610, thereby to cause the latter relay to restore. Upon restoring, the pulse relay R610 interrupts, at the contacts 611, a further point in the previously traced holding circuit for energizing the winding thereof. Finally, the cycle relay R620 recompletes, at the contacts 623, the previously traced holding circuit for energizing the winding of the pulse relay R600.

In view of the foregoing explanation of the mode of operation and restoration of the cycle relays R620 and R630 and the pulse relays R600 and R610, it will be understood that these relays occupy operated and restored positions in accordance with time sequence, as indicated below. During a first time interval the cycle relay R630 and the pulse relay R600 occupy operated positions while the cycle relay R620 and the pulse relay R610 occupy restored positions; during a second time interval the cycle relays R630 and R620 and the pulse relay R600 occupy operated positions while the pulse relay R610 occupies a restored position; during a third time interval the cycle relay R620 and the pulse relays R600 and R610 occupy operated positions while the cycle relay R630 occupies a restored position; during a fourth time interval the pulse relay R610 occupies an operated position while the cycle relays R630 and R620 and the pulse relay R600 occupy restored positions and during a fifth time interval the cycle relay R630 and the pulse relays R600 and R610 occupy operated positions while the cycle relay R620 occupies a restored position. It is noted that the fifth time interval corresponds almost precisely to the first time interval and that the ninth time interval will correspond precisely to the fifth time interval; that the sixth, seventh and eighth time intervals will correspond precisely to the second, third and fourth time intervals; whereby the cycle of operation and restoration of the cycle relays R620 and R630 and the pulse relays R600 and R610 will be repeated continuously as long as the main master impulse generator 22 is in operation.

Consider now the pulses transmitted by the main master impulse generator 22 incident to the

cycle of operation and restoration of the cycle relays R620 and R630 and the pulse relays R600 and R610. An obvious path is completed for connecting ground potential to the odd pickup pulse lead C576 when the cycle relays R620 and R630 occupy restored positions and the pulse relay R610 occupies an operated position; while an obvious path is completed for connecting ground potential to the even pulse pickup lead C685 when the cycle relays R620 and R630 and the pulse relay R600 occupy operated positions. Similarly, an obvious path is completed for connecting ground potential to the odd dial pulse lead C577 when the pulse relay R600 occupies an operated position; while an obvious path is completed for connecting ground potential to the even dial pulse lead C687 when the pulse relay R610 occupies an operated position. Finally, an obvious path is completed for connecting ground potential to the odd revertive pulse lead C574 when the cycle relay R630 and the pulse relay R600 occupy operated positions; while an obvious path is completed for connecting ground potential to the even revertive pulse lead C686 when the cycle relay R630 occupies a restored position and the pulse relay R610 occupies an operated position.

Consider now the cycle of connecting ground potential to the odd and even pulse leads, in view of the cycle of operation and restoration of the cycle relays R620 and R630 and the pulse relays R600 and R610, after operation of the main master impulse generator 22 has been initiated. During a first time interval, ground potential is connected to the odd pulse pickup lead C576, to the even revertive pulse lead C686 and to the even dial pulse lead C687; during a succeeding second time interval ground potential is connected to the odd revertive pulse lead C574, to the even dial pulse lead C687 and to the odd dial pulse lead C577; during a succeeding third time interval ground potential is connected to the even pulse pickup lead C685, to the odd revertive pulse lead C574 and to the odd dial pulse lead C577; during a succeeding fourth time interval ground potential is connected to the even revertive pulse lead C686, to the even dial pulse lead C687 and to the odd dial pulse lead C577; during a succeeding fifth time interval ground potential is connected to the odd pickup pulse lead C576, to the even revertive pulse lead C686 and to the even dial pulse lead C687. It is noted that the above-mentioned first and fifth time intervals correspond precisely, the fifth time interval constituting the beginning of a new cycle of operation of the main master impulse generator 22.

In view of the foregoing explanation of the cycle of operation of the main master impulse generator 22, it will be understood that ground potential is always connected to the pickup pulse lead in a given group of pulse leads prior to the connection of ground potential to the dial pulse lead and to the revertive pulse lead in the given group; that subsequently ground potential is connected substantially simultaneously to the dial pulse lead and the revertive pulse lead in the given group; that still subsequently ground potential is disconnected from the revertive pulse lead in the given group; and that, finally, ground potential is disconnected from the dial pulse lead in the given group. Thereafter, the cycle of operation is repeated. Further it is noted that the main master impulse generator 22 operates to cause the previously explained time relationship between the connection of ground potential to and the disconnection of ground potential

from the pickup pulse lead, the dial pulse lead and the revertive pulse lead in each group of pulse leads to be maintained in order properly to control the repeaters in the two subgroups of repeaters associated therewith, in the manner previously explained. Finally, it is noted that the operation of the auxiliary master impulse generator 23 is substantially identical to that of the main master impulse generator 22, explained above.

When all of the repeaters in the associated group of repeaters are idle or have been completely controlled in the manner previously explained, ground potential is removed from the start lead C575, thereby to interrupt the previously traced circuit for energizing the winding of the lockout relay R660 and the previously traced circuits for energizing the windings of the start relay R640, whereupon the latter relays restore. Upon restoring, the lockout relay R660 recompletes, at the contacts 663, the previously traced original holding circuit for energizing in series the upper and lower windings of the hold relay R670 and interrupts, at the contacts 661 and 662, the various circuits for energizing the windings of the cycle relays R620 and R630 and the pulse relays R600 and R610, thereby to cause each of the relays mentioned to restore. Also when ground potential is removed from the start conductor C575 the previously traced paths for short-circuiting the condensers 644 and 645 are interrupted, thereby to cause the condensers 644 and 645 to be charged and the timing relay R650 to restore, as previously explained. Finally, upon restoring, the start relay R640 interrupts, at the contacts 641, the previously mentioned circuit for illuminating the signal lamp L617, thereby to indicate to the exchange attendant that the main master impulse generator 22 is not operating.

Conclusions

From the foregoing it is apparent that a telephone system is provided which comprises improved switching apparatus, including selector repeaters and other repeaters for completing connections between telephone lines; wherein the selector repeaters are controlled by an improved key sender arrangement and the other repeaters are governed jointly under the control of an improved key sender arrangement and an improved master impulse generator commonly associated with the other repeaters.

While there has been described what is at present considered to be the preferred embodiment of the invention, it will be understood that various modifications may be made therein and it is intended to cover in the appended claims all such modifications as fall within the true spirit and scope of the invention.

What is claimed is:

1. In a telephone system, a trunk including first and second line conductors, switching apparatus having access to said trunk, an automatic switch terminating said trunk, a plurality of lines accessible to said automatic switch, means for causing said switching apparatus to seize said trunk when said trunk is idle, means controlled by the seizure of said trunk for impressing a predetermined potential upon the first line conductor of said trunk, means controlled when said predetermined potential is impressed upon the first line conductor of said trunk for conditioning said automatic switch, means controlled when said automatic switch is conditioned for rendering busy said trunk, means for operating said

automatic switch after it is conditioned, thereby to cause said automatic switch to seize one of said lines, means for initiating the release of said automatic switch, said automatic switch being so connected and arranged that it is adapted to be completely released when the release thereof is initiated, means controlled in the event said automatic switch fails completely to release for impressing a predetermined potential upon the second line conductor of said trunk, and means controlled when said predetermined potential is impressed upon the second line conductor of said trunk for rendering busy said trunk.

2. In a telephone system, a trunk including first and second line conductors, switching apparatus having access to said trunk, an automatic switch terminating said trunk, a plurality of lines accessible to said automatic switch, means for causing said switching apparatus to seize said trunk when said trunk is idle, means controlled by the seizure of said trunk for impressing a predetermined potential upon the first line conductor of said trunk, means controlled when said predetermined potential is impressed upon the first line conductor of said trunk for conditioning said automatic switch and for impressing a first predetermined potential upon the second line conductor of said trunk, means controlled when said predetermined potential is impressed upon the first line conductor of said trunk and said first predetermined potential is impressed upon the second line conductor of said trunk for rendering busy said trunk, means for operating said automatic switch after it is conditioned, thereby to cause said automatic switch to seize one of said lines, means for initiating the release of said automatic switch, said automatic switch being so connected and arranged that it is adapted to be completely released when the release thereof is initiated, means controlled in the event said automatic switch fails completely to release for impressing a second predetermined potential upon the second line conductor of said trunk, and means controlled when said second predetermined potential is impressed upon the second line conductor of said trunk for rendering busy said trunk.

3. In a telephone system, a first telephone line, switching apparatus associated with said first telephone line, a trunk accessible to said switching apparatus, an automatic switch terminating said trunk, a plurality of second telephone lines accessible to said automatic switch, means controlled by the presence of a calling condition upon said first telephone line for causing said switching apparatus to seize said trunk when said trunk is idle, means controlled by the seizure of said trunk for conditioning said automatic switch, means controlled when said automatic switch is conditioned for rendering busy said trunk, an operator position, means controllable from said operator position for selectively operating said automatic switch, said automatic switch being operative in a first predetermined manner to seize one of said second telephone lines and in a second predetermined manner without seizing one of said second telephone lines, means included in said automatic switch and controlled by the operation thereof in said second manner for causing the release of said automatic switch, and means controlled by the release of said automatic switch for rendering idle said trunk and for locking out of service said first

telephone line in the event there is a calling condition thereon.

4. In a telephone system, a first telephone line, switching apparatus associated with said first telephone line, a trunk accessible to said switching apparatus, an automatic switch terminating said trunk, a plurality of second telephone lines accessible to said automatic switch, means controlled by the presence of a calling condition upon said first telephone line for causing said switching apparatus to seize said trunk when said trunk is idle, means controlled by the seizure of said trunk for conditioning said automatic switch, means controlled when said automatic switch is conditioned for rendering busy said 10 trunk, an operator position, means controllable from said operator position for selectively operating said automatic switch, said automatic switch being operative in a first predetermined manner to seize one of said second telephone lines and in a second predetermined manner without seizing one of said second telephone lines, means included in said automatic switch and controlled by the operation thereof in said second manner for initiating the release of said automatic switch, said automatic switch being so connected and arranged that it is adapted to be completely released when the release thereof is initiated, means controlled in the event said automatic 20 switch completely releases for rendering idle said 30 trunk, means controlled in the event said automatic switch fails completely to release for maintaining busy said trunk, and means controlled by the initiation of the release of said automatic switch for locking out of service said first telephone line in the event there is a calling condition thereon.

5. In a telephone system, a first telephone line, switching apparatus associated with said first telephone line, a trunk accessible to said switching apparatus, an automatic switch terminating said trunk, a plurality of second telephone lines accessible to said automatic switch, means controlled by the presence of a calling condition upon said first telephone line for causing said switching apparatus to seize said trunk when said trunk is idle, means controlled by the seizure of said trunk for conditioning said automatic switch, means controlled when said automatic switch is conditioned for rendering busy said 50 trunk, an operator position, a calling device controllable from said operator position to transmit different digits, means for selectively operating said automatic switch in accordance with the different digits transmitted from said calling device, said automatic switch being operative in accordance with certain digits transmitted from said calling device to seize different ones of said second telephone lines and operative in accordance with a given digit transmitted from said calling device to effect the release of said automatic switch, and means controlled by the release of said automatic switch for rendering idle said trunk and for locking out of service said first telephone line in the event there is a calling condition thereon.

6. In a telephone system, a telephone station, switching apparatus associated with said telephone station, a trunk accessible to said switching apparatus, an automatic switching terminating said trunk, a plurality of lines accessible to said automatic switch, means controlled by the performance of a call operation at said telephone station for causing said switching apparatus to seize said trunk when said trunk is idle, means

controlled by the seizure of said trunk for conditioning said automatic switch, means controlled when said automatic switch is conditioned for rendering busy said trunk, a register, means for registering different digits in said register, means for selectively operating said automatic switch in accordance with the different digits registered in said register after it is conditioned, thereby to cause said automatic switch to seize different ones of said lines, means controlled by the operation of said automatic switch for clearing said register of a digit registered therein, means controlled by the performance of a release operation at said telephone station for initiating the release of said automatic switch, said automatic switch being so connected and arranged that it is adapted to be released when the release thereof is initiated, means controlled when said automatic switch is released for rendering idle said trunk, and means for positively preventing the release of said automatic switch prior to the clearance of said register.

7. In a telephone system, a telephone station, switching apparatus associated with said telephone station, a trunk accessible to said switching apparatus, an automatic switch terminating said trunk, a plurality of lines accessible to said automatic switch, means controlled by the performance of a call operation at said telephone station for causing said switching apparatus to seize said trunk when said trunk is idle, means controlled by the seizure of said trunk for conditioning said automatic switch, means controlled when said automatic switch is conditioned for rendering busy said trunk, a register, means for registering different digits in said register, means for connecting said register to said automatic switch and for clearing said register of a digit registered therein, means for selectively operating said automatic switch in accordance with the different digits registered in said register after it is conditioned, thereby to cause said automatic switch to seize different ones of said lines, means controlled by the performance of a release operation at said telephone station for initiating the release of said automatic switch, said automatic switch being so connected and arranged that it is adapted to be released when the release thereof is initiated, means controlled when said automatic switch is released for rendering idle said trunk, and means for positively preventing the release of said automatic switch prior to the clearance of said register.

8. In a signaling system, an automatic switch of the two-motion type, a register, means for registering different digits in said register, means for connecting said register to said switch, means for initiating the first motion of said switch, means controlled revertively from said switch in accordance with the first motion thereof for clearing said register of the digit registered therein, whereby said register is cleared of the digit registered therein when the first motion of said switch corresponds to the digit registered in said register, means controlled when said register is cleared of the digit registered therein for arresting the first motion of said switch, means for initiating the second motion of said switch, and means for arresting the second motion of said switch.

9. In a signaling system, an automatic switch of the two-motion step-by-step type, a register, means for registering different digits in said register, means for connecting said register to said switch, means for initiating the first step-by-step

motion of said switch, means controlled revertively from said switch in accordance with the first step-by-step motion thereof for clearing said register of the digit registered therein, whereby said register is cleared of the digit registered therein when the number of steps of the first step-by-step motion of said switch corresponds to the digit registered in said register, means controlled when said register is cleared of the digit registered therein for arresting the first step-by-step motion of said switch, means for initiating the second step-by-step motion of said switch, and means for arresting the second step-by-step motion of said switch.

10. In a signaling system, a register, means for registering different digits in said register, an automatic switch including a switching mechanism and an impulse responsive motor for operating said switching mechanism and an impulse transmitter operative to transmit impulses to said motor, means for connecting said register to said switch, means for initiating operation of said impulse transmitter, means controlled revertively from said switch in accordance with the operation of said impulse transmitter to transmit impulses to said motor for clearing said register of the digit registered therein, whereby said register is cleared of the digit registered therein when the number of impulses transmitted from said impulse transmitter to said motor corresponds to the digit registered in said register, and means controlled when said register is cleared of the digit registered therein for arresting operation of said impulse transmitter.

11. In a signaling system, a register, means for registering different digits in said register, an automatic switch including a switching mechanism and an impulse responsive motor for operating said switching mechanism and an impulse transmitter operative to transmit direct impulses to said motor and revertive impulses to said register, means for connecting said register to said switch, means for initiating operation of said impulse transmitter, and means controlled when the number of revertive impulses transmitted from said impulse transmitter to said register corresponds to the digit registered therein for arresting operation of said impulse transmitter.

12. In a signaling system, a register, means for registering different digits in said register, an automatic switch including a switching mechanism and an impulse responsive motor for operating said switching mechanism and an impulse transmitter of the step-by-step type, said impulse transmitter being operative to transmit a direct impulse to said motor and a revertive impulse to said register upon each step thereof, means for connecting said register to said switch, means for initiating step-by-step operation of said impulse transmitter, and means controlled when the number of revertive impulses transmitted from said impulse transmitter to said register corresponds to the digit registered therein for arresting step-by-step operation of said impulse transmitter.

13. In a telephone system, an automatic switch including a switching mechanism and an impulse responsive motor for operating said switching mechanism and an impulse transmitter operative to transmit impulses to said motor, switching apparatus operative to route a call to said switch, means for operating said switching apparatus, an operator position, means controllable from said operator position for answering

a call on said switch, a register, means controllable from said operator position for registering different digits in said register and for initiating operation of said impulse transmitter, means controlled revertively from said switch in accordance with the operation of said impulse transmitter to transmit impulses to said motor for clearing said register of the digit registered therein, whereby said register is cleared of the digit registered therein when the number of impulses transmitted from said impulse transmitter to said motor corresponds to the digit registered in said register, means controlled when said register is cleared of the digit registered therein for arresting operation of said impulse transmitter, and means controlled by operation of said switching mechanism for extending a call on said switch.

14. In a telephone system, a line, an automatic switch including a switching mechanism and an impulse responsive motor for operating said switching mechanism and an impulse transmitter operative to transmit impulses to said motor, means including switching apparatus operative in response to the presence of a call on said line for routing the call on said line to said switch, an operator position, means controllable from said operator position for answering a call on said switch, a register, means controllable from said operator position for registering different digits in said register and for initiating operation of said impulse transmitter, means controlled revertively from said switch in accordance with the operation of said impulse transmitter to transmit impulses to said motor for clearing said register of the digit registered therein, whereby said register is cleared of the digit registered therein when the number of impulses transmitted from said impulse transmitter to said motor corresponds to the digit registered in said register, means controlled when said register is cleared of the digit registered therein for arresting operation of said impulse transmitter, means controlled by operation of said switching mechanism for extending a call on said switch, means controllable over said line for releasing said switching apparatus, means normally responsive to the release of said switching apparatus for releasing said switch, and means for positively preventing the release of said switch prior to the clearance of said register.

15. In a signaling system, a register, means for registering different digits in said register, a repeater including an impulse transmitter operative to transmit impulses from said repeater, means for connecting said register to said repeater, means for initiating operation of said impulse transmitter, means controlled revertively from said repeater in accordance with the operation of said impulse transmitter for clearing said register of the digit registered therein, whereby said register is cleared of the digit registered therein when the number of impulses transmitted from said repeater corresponds to the digit registered in said register, and means controlled when said register is cleared of the digit registered therein for arresting operation of said impulse transmitter.

16. In a signaling system, a register, means for registering different digits in said register, a repeater including impulsive apparatus operative to transmit switch control impulses and register control impulses at a predetermined rate, means for connecting said register to said repeater, means for initiating operation of said impulsive

apparatus, and means controlled when the number of register control impulses transmitted from said impulsive apparatus to said register corresponds to the digit registered therein for arresting operation of said impulsive apparatus.

17. In a signaling system, a register, means for registering different digits in said register, a repeater including a first relay operative intermittently to transmit switch control impulses and a second relay operative intermittently to transmit register control impulses, means for connecting said register to said repeater, means for initiating operation of said relays and for causing said relays to operate at a predetermined rate, and means controlled when the number of register control impulses transmitted from said second relay to said register corresponds to the digit registered therein for arresting operation of said relays.

18. In a signaling system, a number of registers, means for registering different digits in said registers, a repeater, switching means operative through a number of cycles successively to connect and disconnect said registers and said repeater, said switching means being operative through a given cycle to connect a given register to said repeater and then to disconnect said given register from said repeater, said repeater including an impulse transmitter operative through a cycle to transmit a series of impulses from said repeater, means for initiating a cycle of operation of said switching means, means controlled when a register is connected to said repeater for initiating a cycle of operation of said impulse transmitter, means controlled revertively from said repeater in accordance with the operation of said impulse transmitter for completing a cycle of operation of said switching means, whereupon one of said registers is disconnected from said repeater, said last-mentioned means being controlled when the number of impulses transmitted from said repeater corresponds to the digit registered in the one of said registers, and means controlled when a cycle of operation of said switching means is completed for completing a cycle of operation of said impulse transmitter.

19. In a signaling system, a number of registers, means for registering different digits in said registers, a repeater, switching means operative through a number of cycles successively to reconnect and disconnect said registers and said repeater, said switching means being operative through a given cycle to connect a given register to said repeater and then to disconnect said given register from said repeater, said repeater including an impulse transmitter operative through a cycle to transmit a series of impulses from said repeater, means for initiating a cycle of operation of said switching means, means controlled when a register is connected to said repeater for initiating a cycle of operation of said impulse transmitter, means controlled revertively from said repeater in accordance with the operation of said impulse transmitter for completing a cycle of operation of said switching means and then for initiating another cycle of operation of said switching means, whereupon one of said registers is disconnected from said repeater and then another of said registers is connected to said repeater, said last-mentioned means being controlled when the number of impulses transmitted from said repeater corresponds to the digit registered in the one of said registers, and means controlled when a cycle of operation of said

switching means is completed for completing a cycle of operation of said impulse transmitter.

20. In a signaling system, a register, means for registering different digits in said register, a repeater including an impulse transmitter operative to transmit a series of switch control impulses and a series of register control impulses at a predetermined rate, an impulse generator, means for connecting said register to said repeater and for connecting said repeater to said impulse generator, means controlled when said repeater is connected to said impulse generator for initiating operation of said impulse transmitter, means controlled when the number of impulses in the series of register control impulses transmitted from said impulse transmitter to said register corresponds to the digit registered therein for disconnecting said register from said repeater, and means controlled when said register is disconnected from said repeater for arresting operation of said impulse transmitter and for disconnecting said repeater from said impulse generator.

21. In a signaling system, a register, means for registering different digits in said register, a repeater including an impulse transmitter operative to transmit a series of switch control impulses and a series of register control impulses at a predetermined rate, means for connecting said register to said repeater, an impulse generator, means controlled when said register is connected to said repeater for connecting said repeater to said impulse generator, means controlled when said repeater is connected to said impulse generator for initiating operation of said impulse transmitter, means controlled when the number of impulses in the series of register control impulses transmitted from said impulse transmitter to said register corresponds to the digit registered therein for disconnecting said register from said repeater, means controlled when said register is disconnected from said repeater for arresting operation of said impulse transmitter, and means controlled when operation of said impulse transmitter is arrested for disconnecting said repeater from said impulse generator.

22. In a signaling system, a register, means for registering different digits in said register, a repeater including an impulse transmitter operative to transmit a series of switch control impulses and a series of register control impulses at a predetermined rate, means for connecting said register to said repeater, an impulse generator, means controlled when said register is connected to said repeater for connecting said repeater to said impulse generator and for initiating operation of said impulse generator, means controlled by the operation of said impulse generator when said repeater is connected thereto for initiating operation of said impulse transmitter, means controlled when the number of impulses in the series of register control impulses transmitted from said impulse transmitter to said register corresponds to the digit registered therein for disconnecting said register from said repeater, means controlled when said register is disconnected from said repeater for arresting operation of said impulse transmitter, and means controlled when operation of said impulse transmitter is arrested for disconnecting said repeater from said impulse generator and for arresting operation of said impulse generator.

23. In a signaling system, a register, means for registering different digits in said register, a repeater including an impulse transmitter operative to transmit a series of switch control impulses

and a series of register control impulses at a predetermined rate, means for connecting said register to said repeater, an impulse generator operative repeatedly through a cycle to transmit a connect impulse and then at least one control impulse, means controlled when said register is connected to said repeater for conditioning said repeater, means controlled by the transmission of a connect impulse from said impulse generator when said repeater is conditioned for connecting said repeater to said impulse generator, means controlled by the transmission of control impulses from said impulse generator for operating said impulse transmitter, means controlled when the number of impulses in the series of register control impulses transmitted from said impulse transmitter to said register corresponds to the digit registered therein for disconnecting said register from said repeater, means controlled when said register is disconnected from said repeater for arresting operation of said impulse transmitter, and means controlled when operation of said impulse transmitter is arrested for disconnecting said repeater from said impulse generator.

24. In a signaling system, a repeater including a normally ineffective impulse transmitter operative to transmit a series of switch control impulses at a substantially constant rate, an impulse generator associated with said repeater and operative continuously to transmit control impulses at a predetermined rate, means for operating said impulse generator, means included in said repeater and controlled when said impulse transmitter is rendered effective for causing operation of said impulse transmitter in response to the control impulses transmitted from said impulse generator, and means including a calling device for selectively rendering effective during different time intervals said impulse transmitter.

25. In a signaling system, a repeater including an impulse transmitter operative to transmit a series of switch control impulses at a substantially constant rate, an impulse generator operative continuously to transmit control impulses at a predetermined rate, means for operating said impulse generator, means included in said repeater and controlled when said repeater is connected to said impulse generator for causing operation of said impulse transmitter in response to the control impulses transmitted from said impulse generator, and means including a calling device for selectively connecting during different time intervals said repeater to said impulse generator.

26. In a signaling system, a plurality of repeaters, each of said repeaters including a normally ineffective impulse transmitter operative to transmit a series of switch control impulses at a substantially constant rate, an impulse generator commonly associated with said repeaters and operative to transmit control impulses, means for controlling the operation of said impulse generator, means included in each of said repeaters and controlled when the impulse transmitter therein is rendered effective for causing operation of the impulse transmitter in response to the control impulses transmitted from said impulse generator, a plurality of calling devices, means for selectively connecting said calling devices to said repeaters, and means included in each of said repeaters and controllable from a calling device connected to the repeater for selectively rendering effective during different time intervals the impulse transmitter in the repeater.

27. In a signaling system, a plurality of repeaters, each of said repeaters including a normally ineffective impulse transmitter operative to transmit a series of switch control impulses at a substantially constant rate, an impulse generator commonly associated with said repeaters and operative to transmit control impulses, control means governed when the impulse transmitter in any one of said repeaters is rendered effective for initiating operation of said impulse generator and governed when the impulse transmitter in each of said repeaters is ineffective for arresting operation of said impulse generator, means included in each of said repeaters and controlled when the impulse transmitter therein is rendered effective for causing operation of the impulse transmitter in response to the control impulses transmitted from said impulse generator, a plurality of calling devices, means for selectively connecting said calling devices to said repeaters, and means included in each of said repeaters and controllable from a calling device connected to the repeater for selectively rendering effective during different time intervals the impulse transmitter in the repeater.

28. In a signaling system, a plurality of repeaters, each of said repeaters including an impulse transmitter operative to transmit a series of switch control impulses at a substantially constant rate, an impulse generator operative to transmit control impulses at a predetermined rate, means for controlling the operation of said impulse generator, means included in each of said repeaters and controlled when the repeater is connected to said impulse generator for causing operation of the impulse transmitter therein in response to the control impulses transmitted from said impulse generator, a plurality of calling devices, means for selectively connecting said calling devices to said repeaters, and means included in each of said repeaters and controllable from a calling device connected to the repeater for selectively connecting during different time intervals the repeater to said impulse generator.

29. In a signaling system, a plurality of repeaters, each of said repeaters including an impulse transmitter operative to transmit a series of switch control impulses at a substantially constant rate, an impulse generator operative to transmit control impulses at a predetermined rate, control means governed when any one of said repeaters is connected to said impulse generator for initiating operation of said impulse generator and governed when each of said repeaters is disconnected from said impulse generator for arresting operation of said impulse generator, means included in each of said repeaters and controlled when the repeater is connected to said impulse generator for causing operation of the impulse transmitter therein in response to the control impulses transmitted from said impulse generator, a plurality of calling devices, means for selectively connecting said calling devices to said repeaters, and means included in each of said repeaters and controllable from a calling device connected to the repeater for selectively connecting during different time intervals the repeater to said impulse generator.

30. In a signaling system, a repeater including an impulse transmitter operative to transmit a series of switch control impulses, an impulse generator operative continuously to transmit control impulses, means for operating said impulse generator, a calling device, means for connecting said calling device to said repeater

over a path independent of said impulse generator, means including a control network in said repeater for causing operation of said impulse transmitter in response to control impulses transmitted from said impulse generator, and means including said calling device for selectively governing said control network, thereby selectively to govern the number of switch control impulses in the series of switch control impulses transmitted from said repeater.

31. In a signaling system, a repeater including a control network and an impulse transmitter operative to transmit a series of switch control impulses, an impulse generator operative repeatedly through a cycle to transmit a start impulse and then at least one control impulse, means for operating said impulse generator, said control network being operative to condition said impulse transmitter in response to a start impulse transmitted from said impulse generator and then to cause operation of said impulse transmitter after it is conditioned in response to control impulses transmitted from said impulse generator, thereby to prevent operation of said impulse transmitter to transmit a series of switch control impulses including a mutilated switch control impulse, and means for selectively operating said control network, thereby to cause said repeater to transmit a series of switch control impulses comprising different numbers of switch control impulses.

32. In a signaling system, a repeater including a control network and an impulse transmitter operative repeatedly to transmit a number of series of switch control impulses, an impulse generator operative repeatedly through a cycle to transmit a start impulse and then at least one control impulse, means for operating said impulse generator, said control network being operative to condition said impulse transmitter in response to a start impulse transmitted from said impulse generator and then to cause operation of said impulse transmitter after it is conditioned in response to control impulses transmitted from said impulse generator, thereby to prevent operation of said impulse transmitter to transmit a series of switch control impulses including a mutilated switch control impulse, and means for repeatedly and selectively operating said control network, thereby to cause said repeater to transmit a number of series of switch control impulses, each series of switch control impulses comprising the same or a different number of switch control impulses.

33. In a signaling system, a plurality of repeaters, each of said repeaters including an impulse transmitter operative to transmit a series of switch control impulses, an impulse generator commonly associated with said repeaters and operative to transmit control impulses, means for operating said impulse generator, means including a control network in each of said repeaters for causing operation of the impulse transmitter in the repeater in response to the control impulses transmitted from said impulse generator, and means for selectively governing the control network in each of said repeaters, thereby selectively to govern the number of switch control impulses in the series of switch control impulses transmitted from the repeater.

34. In a signaling system, a plurality of repeaters, each of said repeaters including a control network and an impulse transmitter operative to transmit a series of switch control impulses, an impulse generator commonly asso-

ciated with said repeaters and operative repeatedly through a cycle to transmit a start impulse and then at least one control impulse, means for operating said impulse generator, the control network in each of said repeaters being operative to condition the impulse transmitter therein in response to a start impulse transmitted from said impulse generator and then to cause operation of the impulse transmitter therein after it is conditioned in response to control impulses transmitted from said impulse generator, thereby to prevent operation of the impulse transmitter in the repeater to transmit a series of switch control impulses including a mutilated switch control impulse, and means for selectively operating the control network in each of said repeaters, thereby to cause the repeater to transmit a series of switch control impulses comprising different numbers of switch control impulses.

35. In a signaling system, a plurality of repeaters, each of said repeaters including a control network and an impulse transmitter operative repeatedly to transmit a number of series of switch control impulses, an impulse generator commonly associated with said repeaters and operative repeatedly through a cycle to transmit a start impulse and then at least one control impulse, means for operating said impulse generator, the control network in each of said repeaters being operative to condition the impulse transmitter therein in response to a start impulse transmitted from said impulse generator and then to cause operation of the impulse transmitter after it is conditioned in response to control impulses transmitted from said impulse generator, thereby to prevent operation of the impulse transmitter in the repeater to transmit a series of switch control impulses including a mutilated switch control impulse, and means for repeatedly and selectively operating the control network in each of said repeaters, thereby to cause the repeater to transmit a number of series of switch control impulses, each series of switch control impulses comprising the same or a different number of switch control impulses.

36. In a signaling system, a plurality of repeaters, each of said repeaters being operative to transmit a series of switch control impulses, means including an impulse generator commonly associated with said repeaters for operating said repeaters, and means for selectively controlling the operation of each of said repeaters, thereby selectively to control the number of switch control impulses included in the series of switch control impulses transmitted from each of said repeaters.

37. In a signaling system, a plurality of repeaters, each of said repeaters being operative to transmit a series of switch control impulses, an impulse generator commonly associated with said repeaters and adapted when operating to operate each of said repeaters, means for initiating operation and for arresting operation of each of said repeaters, thereby selectively to control each of said repeaters in order selectively to govern the number of switch control impulses included in the series of switch control impulses transmitted from each of said repeaters, and means governed when operation of one of said repeaters is initiated for initiating operation of said impulse generator and governed when operation of each of said repeaters is arrested for arresting operation of said impulse generator.

38. A control network comprising first and

second relays, first and second conductors, means for cyclically impressing alternately upon said conductors a predetermined potential, means controlled when said potential is impressed upon said first conductor while said first relay and second relay are restored for causing operation of said first relay, means controlled when said potential is impressed upon said second conductor while said first relay is operated and said second relay is restored for causing operation of said second relay, means controlled when said potential is impressed upon said first conductor while said first relay and said second relay are operated for causing restoration of said first relay, and means controlled when said potential is impressed upon said second conductor while said first relay is restored and said second relay is operated for causing restoration of said second relay.

39. A control network comprising first and second relays, first and second conductors, means for impressing cyclically upon said first conductor and then upon said second conductor a predetermined potential, means controlled each odd time said potential is impressed upon said first conductor for causing operation of said first relay, means controlled each odd time said potential is impressed upon said second conductor for causing operation of said second relay, means controlled each even time said potential is impressed upon said first conductor for causing restoration of said first relay, and means controlled each even time said potential is impressed upon said second conductor for causing restoration of said second relay.

40. An impulse generator comprising first and second relays, first and second conductors, means operative cyclically at a predetermined rate for impressing upon said first conductor and then upon said second conductor a predetermined potential, means controlled each odd time said potential is impressed upon said first conductor for causing operation of said first relay, means controlled each odd time said potential is impressed upon said second conductor for causing operation of said second relay, means controlled each even time said potential is impressed upon said first conductor for causing restoration of said first relay, and means controlled each even time said potential is impressed upon said second conductor for causing restoration of said second relay, whereby said first and second relays are controlled cyclically at one-half said predetermined rate, and an impulse transmitting network governed by the cyclical control of said first and second relays.

41. An impulse generator comprising first and second relays, first and second conductors, means operative cyclically at a predetermined rate for

impressing upon said first conductor and then upon said second conductor a predetermined potential, means controlled each odd time said potential is impressed upon said first conductor for causing operation of said first relay, means controlled each odd time said potential is impressed upon said second conductor for causing operation of said second relay, means controlled each even time said potential is impressed upon said first conductor for causing restoration of said first relay, means controlled each even time said potential is impressed upon said second conductor for causing restoration of said second relay, whereby said first and second relays are controlled cyclically at one-half said predetermined rate, an impulse transmitting network governed by the cyclical control of said first and second relays, a signal, and means governed by a predetermined departure by said first and second relays from cyclical control at one-half said predetermined rate for controlling said signal.

42. A control network comprising a relay, first and second condensers, a first series circuit for charging said first condenser and for energizing said relay, a second series circuit for charging said second condenser and for energizing said relay, a first series path for discharging said first condenser and for energizing said relay, a second series path for discharging said second condenser and for energizing said relay, cyclically operating control means for completing said first circuit and said second path and then for completing said second circuit and said first path, thereby intermittently to energize said relay, and means governed by the intermittent energization of said relay.

43. A control network comprising a relay, first and second condensers, a first series circuit for charging said first condenser and for energizing said relay, a second series circuit for charging said second condenser and for energizing said relay, a first series path for discharging said first condenser and for energizing said relay, a second series path for discharging said second condenser and for energizing said relay, cyclically operating control means for completing said first circuit and said second path and then for completing said second circuit and said first path, thereby intermittently to energize said relay at a predetermined rate, the capacitance of said condensers and the impedance of said relay being so proportioned and related that said relay is operated intermittently incident to intermittent energization thereof only in the event said predetermined rate of intermittent energization of said relay is within given limits, and means governed by the intermittent operation of said relay.
